UNITED STATES PATENT OFFICE.

CARLOS HOLLY, OF LOCKPORT, NEW YORK, ASSIGNOR TO F. N. BURT COMPANY, LIMITED, OF BUFFALO, NEW YORK, A CORPORATION OF ONTARIO, CANADA.

SHELL-MACHINE.

1,201,822.

Specification of Letters Patent.

Patented Oct. 17, 1916.

Application filed June 24, 1912, Serial No. 705,512. Renewed March 11, 1916. Serial No. 83,685.

To all whom it may concern:

Be it known that I, CARLOS HOLLY, a citizen of the United States, residing at Lockport, in the county of Niagara and State of New York, have invented certain new and useful Improvements in Shell-Machines, of which the following is a full, clear, and exact description, such as will enable others skilled in the art to which it appertains to 10 make and use the same.

This invention relates to methods and machines for the manufacture of tubes, and with respect to its more specific features, to a machine for the production of shells for 15 boxes from continuous webbing of paper or similar material.

One object of the invention is the production of a practical machine for the rapid manufacture of shells of the character described.

Another object of the invention is the provision of a mechanism for the efficient production of shells from a relatively thick and stiff body web and a relatively thin and 25 flexible cover web.

Another object of the invention is the provision of a simple and efficient mechanism for feeding the webs into the special relationship required for their assembly into 30 blanks.

Another object of the invention is the provision of a practical means for simultaneously folding the cover web over the oppositely disposed edges of a blank.

Another object of the invention is the provision of improvements in mechanism whereby a blank is folded into and secured in tubular form or shell and the cover disposed thereon around the ends of the tube 40 or shell.

Another object is the provision of an improved and practical method for successively making shell blanks, and especially for making such blanks from continuous 45 webs and folding and securing them in shell form, the edges of the shell being nicely covered.

Another object of the invention is the provision of a practical cutting mechanism.

Another object of the invention is the provision of efficient gluing devices for the webs.

Other objects will be in part obvious and in part pointed out hereinafter.

55 The invention accordingly consists in the

several steps and the relation and order of one or more of such steps with relation to each of the others thereof, and in the features of construction, combinations of elements and arrangement of parts, which will 60 be exemplified in the method hereinafter disclosed and the construction hereinafter set forth, and the scope of the application of each of which will be indicated in the following claims.

65 While the production of shells of various cross sections or shapes is contemplated and within the purview of this invention, the embodiment herein described has for its object the production of shells of angular and especially rectangular cross section.

70 The body web is composed of straw board, card board or some material capable of being bent to the desired shape and comprises a web of the material of such width that 75 when folded a shell of the desired dimensions will result. The cover web may be, and in this instance is, of thin and more flexible material than the body web and preferably one of the surfaces of the cover 80 web is smooth or ornamental, its other surface being preferably unglazed, in order to provide for efficient gluing.

85 One of the prime objects sought by this invention may be stated to be the manufacture of nicely covered shells from continuous webs of the character referred to, and to do this continuously by the automatic operation of the machine, the operator being required only to renew the supply of webbing or of glue as they become exhausted in the production of the articles.

90 In the accompanying drawings forming a part of this specification, and wherein similar reference characters refer to similar parts throughout the several views, Figure 1 represents a side elevation of the machine; Fig. 2 represents the machine in elevation from the opposite side; Fig. 3 represents the front of the machine; Fig. 4 is a view looking at the rear of the machine and showing the relationship of some of the parts; Fig. 5 is a side elevation of the rear portion of the machine, partly in section, and illustrating the guide mechanism for the body web where it enters the machine, and also illustrating the body web gluing mechanism; Fig. 6 is a top plan view of the devices shown in Fig. 5; Fig. 7 is a rear view of some of the parts shown in Fig. 5; Fig. 8 100

95

100

110

is a partly sectional view showing the cam operating mechanism for the body web gluer; Fig. 9 is a detailed plan view of the body web gluer; Fig. 10 is a detailed rear elevation of said gluer; Figs. 11, 12 and 13 are detailed views showing the pressing rollers for holding the body web against the guide fingers; Figs. 14 and 15 represent in plan and in sectional elevation the arrangement of the more prominent operating shafts of the machine; Figs. 16, 17 and 18 represent in sectional elevation, in plan and in front view, the supporting table and certain devices operating adjacent thereto for assembling the webs and slitting the cover web; Fig. 19 is a detailed sectional view and elevation disclosing the feed rollers for the cover web, and also the relative arrangement of the cutting mechanism for each web; Fig. 20 is a side elevation of the cutters and their operating parts; Fig. 21 illustrates, in side elevation, the mechanism for folding the cover web over the edges of the body web and the blank cut therefrom, and the operating mechanism therefor; Fig. 22 is a view taken from the front of the parts shown in Fig. 21; Fig. 23 is a perspective view of the combined folder and presser; Fig. 24 is a vertical section through the same; Figs. 25 and 26 are details showing one of the rollers for pressing the cover web and body web together; Fig. 27 is a side elevation showing the mechanism for operating one of the web feeding devices employed in this machine; Fig. 28 is a top plan view of parts shown in Fig. 27; Fig. 29 is a front elevation of a pair of grippers; Fig. 30 is a view looking from the opposite side in Fig. 27 and showing the pawl and ratchet mechanism whereby the body web feeding rollers are operated at proper times; Fig. 31 is a detailed sectional view through a side of the table, showing the devices for guiding and holding the gripper carrying rod; Figs. 32, 33, 34 and 35 represent in different views the blank carrier device and details thereof; Fig. 36 is a detailed view showing the operating mechanism for the segmental flange guides; Fig. 37 is a view looking at right angles to Fig. 36 and showing the slack producing bar for the cover web; Fig. 38 is a view showing the operating connections of the slitter; Fig. 39 shows the devices for holding the webs while being cut; Figs. 40 and 41 are, respectively, side and front views illustrating a movable guide bar; Fig. 42 represents an elevation of the mechanism for feeding and folding the shell blank and pressing and delivering the same; Fig. 43 is an end elevation of the lower folding mechanism for the shell blank; Fig. 44 is a vertical section through the lower folder; Fig. 45 is a detail; Fig. 46 is an elevation of the shell pressing mechanism; Figs. 47 and 48 are detail views of the shell pressing mech- anism from different points of view; Fig. 49 is a horizontal section through the former, showing the stripper or shell delivering device; Fig. 50 is a side elevation of the upper folding mechanism and associated parts; Fig. 51 is a longitudinal transverse section through the upper folding mechanism; Fig. 52 is a horizontal transverse section through the main press head of the upper folder; Fig. 53 is an end elevation of the upper folder; Fig. 54 is a section through the upper folder, showing the auxiliary press head in plan; Fig. 55 is an end elevation showing an auxiliary folder; Figs. 56 and 57 are plan and side elevations of the mechanism shown in Fig. 55; Fig. 58 is a side elevation of the blank trimming device, showing the associated moistener and clearer; Fig. 59 is a front elevation, partly in section, of the mechanism disclosed in Fig. 58; Fig. 60 is a detail view; Figs. 61 and 62 represent, in side elevation and in end elevation, respectively, the cover web gluing and tensioning devices; Fig. 63 is a plan view of the body web glue pot and its associated parts; Fig. 64 is a detail of a portion of the tension device for the body web; Figs. 65 to 72^A inclusive illustrate steps in the formation of the shell; Fig. 73 illustrates the assembled body web and cover web before folding; Fig. 74 illustrates the assembled cover blank and body blank assembled into a shell blank; Fig. 75 illustrates the shell blank and shows, in dotted lines, the part cut off by the trimming blade; Fig. 76 is an end view of the shell, showing the unfolded tongues; and Fig. 77 is an end view of the shell stop.

A preferred machine for carrying out the method is illustrated in the accompanying drawings, and referring now more in detail thereto, the frame of the machine comprises a rectangular body portion 1 having horizontally spaced sides; two strong legs 2 bolted to the body portion and to the floor, and extending above the body portion and connected by a cross piece 3 bracing the frame and forming a support for some of the parts, as will hereinafter appear. Above the body portion is a stationary horizontal table 4 supported at its front portion by a cross bar 5 bolted to the legs and at its rear portion by an upright 6. The table is angular in cross section and is provided with laterally disposed horizontal flanges 7 on each side adapted to serve as a support for one or more of the co-operatively associated devices.

Main driving mechanism.—The numeral 8 represents the horizontal driving shaft journaled in the body portion and which is adapted to be continuously driven from pulley 9 through a suitable shiftable clutch connection between said pulley and the shaft 8 operated from connecting rod 10 and hand 130

lever 11. On the shaft 8 is a bevel gear 12 meshing with a larger similar gear 13 on a horizontal counter-shaft 14 journaled in cross pieces of the casting; this latter shaft 5 carrying a mutilated gear, cams, etc., for operating different parts of the mechanism, as will hereinafter appear. The shaft 14 at its opposite end carries a beveled pinion 15 operating a similar pinion 16 upon a third 10 horizontal shaft 17, also provided with several cams which take part in the operation of the machine.

Body web.—A body web *a* of the character hereinbefore referred to is continuously supplied 15 from a suitable source and is preferably longitudinally grooved intermediate its edges parallel with its direction of feed, and scarfed at its edges in order that the blanks may be more efficiently folded into 20 tubular form and their edges secured together. Preferably the grooving is effected by removing the material of the web by means of grinding wheels, such as set forth in applicant's prior application filed April 25 24, 1909, Serial No. 492,029, and the scarfing may be effected in the same machine, but in the present case the scarfs are provided on the same face of the web instead of on opposite faces, as in the prior machine. The 30 body web is fed into the machine in such a manner that when the blanks obtained therefrom are folded, the scored face will be inside the tube or shell formed. In the present embodiment four lines of scores are made 35 in the cover web, one at *b* at a distance from the edge corresponding to the width of the smaller side of the shell; another at *c* spaced therefrom corresponding to the width of the larger side of the shell; another at *d* spaced 40 from the latter the width of the smaller side, and another at *e* spaced from the last a distance corresponding to the width of the larger side. Between the last score *e* and the adjacent edge of the web a distance less 45 than the smaller side of the shell is preferably provided. In the completed shell this smaller portion lies beneath or inside the larger width at the other end, so that the uniform appearance shall be unmarked by a 50 joint except at the extreme edge, where it will not readily be noticed. The scarfed edges of the web in the completed box substantially overlap or are superposed so as to provide a substantially uniform thickness of 55 the shell walls around the box.

Guiding device.—Prepared as thus described, the body web enters the machine adjacent a guiding device, preferably comprising oscillatory curved guide fingers or blades 60 18 mounted on a rock shaft 19 journaled in brackets 20 bolted to the rear end of the table 4 at either side thereof. Coöperatively associated with and generally conforming to the periphery of the guides 18 is a curved 65 guide plate 21, also supported by the brack-

ets and provided with openings 22 opposite the fingers 18. The fingers 18 are adjustably secured upon the rock shaft 19 in alignment with the grooves in the body web, and said shaft 19 is transversely adjustable by 70 means of a nut 23 threaded on the shaft 19 and coöperating with the bracket 20 to move the shaft in one direction, a spring 24 encircling the shaft between the bracket 20 and the hub of one of the guide fingers, and 75 serving to move the shaft in the opposite direction. A lock nut 25 may be employed to maintain the shaft in adjusted position. Secured at one end of the rock shaft is an arm 26 having a pin 27 engaging a slot in a 80 connecting rod 28 pivoted at its opposite end to an arm of a rock lever 29 fulcrumed on the frame and operated by means of a cam 30 on a short transverse shaft 31 journaled above the body 1 and continuously 85 driven by a sprocket wheel 32 and chain 33 from a sprocket wheel 34 secured to the driving shaft 8. To insure this engagement a cross bar 35 is supported adjacent the periphery of the fingers in the brackets 20, 90 and rotatable pins 36 passing through said cross bar provide a support for rollers 37 supported in hangers 38 pivoted to the pins on one side of the cross bar, there being a spring 39 intermediate the roller support 95 and an abutment block 40 secured to the pin at the opposite side of said bar. The rollers 37 are located opposite the openings 22 and engage the surface of the body web opposite the grooves and press the same against the fingers 18, whereby the web is efficiently 100 guided by the fingers. The face of the cross bar 35 is flattened, in order to maintain the rollers in proper alignment with the grooves of the web.

The body web having been threaded between the fingers 18 and the curved plate 21, rests upon the upper surface of the table 4 in a flat condition and is drawn intermittently therewith by a feeding mechanism 105 presently described. The cam operating mechanism of the segmental guide blades is so designed and timed that, as the body web is fed, the blades move therewith, thus guiding the web without offering any frictional 110 resistance to its motion. After the movement of the web and while it is at rest, the guide fingers are returned to initial position, moving at this time relatively to the web.

The cover web *f* is held in a roll below the 115 table and is directly unrolled by a slack-producing device, so that the main feeding device does not have to pull against the inertia of the entire roll of web. The cover web passes over a glue pot, where glue is applied 120 over the full width of its unglazed surface. When the body web and the cover web are superposed in the operation of the machine, the cover web lies beneath the body web, one lateral edge of the cover web being pref- 125 130

erably within the corresponding edge of the body web and near the score at that point, while the other lateral edge of the cover web extends beyond the opposite edge of the body web. Ordinarily this latter edge of the cover web will project so far beyond the body web that it will subsequently be cut or trimmed to define an edge at a proper distance, as will appear.

Gluing mechanism for the scarfed edge.—The body web is introduced into the machine with the wider scarfed face on that side of the machine less apt to be affected by gumming of the parts. Glue is applied to the 15 scarf inside the edge of the web and is subsequently spread preferably to within a short distance of the edge of the web so that in the subsequent operations, including the pressing of the scarfed edges together, a sufficient amount of glue may be forced to the 20 edge of the web to make the joints secure and yet avoid a surplusage at such point. The table 4 adjacent its rear end is provided with a laterally disposed opening below 25 which is disposed a glue pot 41. Passing through opposite walls of the glue pot is a rotary hollow shaft 42 carrying a glue supply roller 43 of a diameter sufficient to dip into the glue in the pot and carry the same to a point above the pot outside the edge of 30 the body web and approximately level with said edge. Passing through the shaft 42 and extending beyond each end thereof is a shaft 44, on one end of which is loosely 35 journaled a pinion 45 between the end face of shaft 42 and a head 46 on shaft 44. The opposite end of shaft 44 carries a large pinion 47 having a pin and slot engagement 40 with the shaft 44 so as to rotate therewith and adjustable longitudinally thereof. A thumb nut 48 is threaded on the shaft 44 and is adapted to bear against the hub of the pinion 47. By operating the thumb nut 48 the pinion 45 may be frictionally clutched 45 to the hollow shaft 42, or unclutched therefrom. The pinion 45 is driven from a gear 49 on shaft 31.

Mounted on the lateral wall of the table 4 is a bracket 49' in which is journaled a 50 stub shaft 50 carrying a pinion 51. Also supported by said bracket are two short horizontal shafts 52 and 53 parallel with the stub shaft and disposed upon either side thereof, each having a pinion 54, 55 at one 55 end meshing with the pinion 51, and parallel cranks 56 and 57 having crank pins engaging sockets in a transversely disposed supporting sleeve 58 in which is journaled a shaft 59 carrying at one end a pinion 60 60 adapted to be engaged with and disengaged from the pinion 47, and at its other end a glue applying roller 61, the edge of which is adapted to roll upon the glue supply roller 43 and receive glue therefrom to be 65 subsequently deposited upon the scored edge

of the body web. The body web passes over the opening in the table and is supported intermediate the front and rear walls of said opening by means of a tongue 62 disposed in alinement with the path of the roller 61. 70 Connected to the pinion 51 is a belt pulley 63 around which passes a belt 64, one end of which is yieldingly connected to a pin 65 on the frame by means of a relatively light spring 66, the other portion of the belt 75 passing beneath the table 4 around an idle roller 67 and connected by a relatively strong spring 68 to the end of a rock arm 69 pivoted to the wall of the glue pot and operated by means of a cam 70 on the shaft 80 31. The pulley 63 and the belt 64 are attached by a pin 70' so as to avoid lost motion between these parts. A spreader is secured to the table in the line of travel of that scarfed edge of the body web which receives the glue from the roller 43, and comprises a plate 71 fixed to the upper surface of the table and having a downwardly projecting toe which contacts with the line of glue supplied by the roller 61. The contacting portion of the toe is inclined forwardly and outwardly so as to deflect some of the glue toward the outer edge of the body web. 90

The operation of the gluing mechanism just described comprises the following: As 95 the shaft 31 rotates, the cam 70 causes the belt 64 to move in one direction, the spring 66 moving the belt in the opposite direction. As the pinion 51 is thus rocked, the glue-applying roller is moved to and from the 100 scarfed surface of the web supported by the tongue 62, and when in contact with the web said web is fed, the roller 61 applying glue thereto during the forward movement of the web. When the glue roller is moved from 105 the web to the supply roller, the pinion 60 will be moved into engagement with the driving pinion 47 and a fresh supply of glue will thereby be deposited upon the roller 61. In order to prevent an undue amount of glue 110 accumulating upon the glue supply roller, a rock arm 72 is disposed adjacent the periphery of the supply roller, being mounted in a bracket 73 and adjustably held in position by a spring 74 encircling a pin 75 provided with a nut 76. The down-turned end of the arm 72 may be adjusted to a position closely adjacent or in actual contact with the periphery of the supply roller, and serves as a gage for the amount of glue, at the 115 same time preventing a surplus amount being delivered to the applying roller 61.

Feed mechanism for body web.—The feed mechanism for the body web is disposed in such a position upon the table as to draw 125 the web from its supply past the scarfed gluing devices and comprises a pair of roughened or knurled feed rollers 77 and 78, between which the web is grasped and by which it is fed forward an amount equal 130

to the length of shell desired, one of said rollers being carried on a shaft rotatably supported beneath the table, and the upper roller 77 carried on a transverse shaft supported in standards 79 and 80 fastened at either side of the table, the table being provided with an opening through which the rollers 77 and 78 engage the body web. The shafts of the feed rollers are provided with 10 intermeshing gears 81 for simultaneously rotating the same in the proper directions.

Body web cutter mechanism.—At a point in the rear of assembly position of the body web and the cover web, the body web is severed at a distance from its front end corresponding with the length of shell desired. The table 4 is cut away or slotted for the passage of the cover web from therebeneath and the rear edge of the slot provides a 20 knife-edge or stationary cutter at the surface of the table which coöperates with a reciprocatory cutter which moves from side to side of the body web in substantially the plane thereof. On the under side of the 25 cross piece 3 and extending transversely of the machine is a dovetailed guide rib 82 supporting a cutter carriage 83 adapted to reciprocate longitudinally of the guide. A circular cutter or disk 84 is suitably journaled in the carriage and properly positioned to coöperate with the cutting edge 85 above referred to. The carriage is reciprocated by means of a connecting rod 86 pivotally connected to one end of a rock lever 30 35 40 45 50 55 60 65 70 75 80 85 90 95 100 105 110 115 120 125 130 135 140 145 150 155 screw threads engaged by a nut 127 which abuts against the lug 126. A coil spring 128 surrounds rod 125 between the lug and pin and exerts its tension to raise the pin 123. 5 The disposition of the links 121 and 124 is such that, when the lever 122 is operated to depress the guide roller and place it in guiding position, the pivotal connections between link 121 and arm 120 will assume position causing the spring 128 to hold a stop plate 129 on the hand lever against the link 121, thus locking the arms 116 in lowered position. By manipulating the nut 127 the angle between the link 121 and the arm 120 10 may be varied so that the guide roller will come to rest in locked position at different elevations. By operating the hand lever in the proper direction link 121 may be turned to unlocked position, whereupon the spring 119 will assist in turning the shaft 115 and in raising the guide roller above the pot, holding the same in raised position.

130 is a glue supply roller having its axle loosely resting in slots in the pot walls and 25 laterally retained by shoulders 131. Roller 130 dips into the glue in the pot and is of a sufficient extent to contact with the full width of the cover web as the latter passes thereover, being turned by the contact of 30 the web therewith as the web is fed.

132 is a scraper bar adapted to contact the glued face of the cover web and supported at one end by a lever 133 mounted on a bracket 134 and held in adjusted position by 35 means of a spring 135 surrounding a rod 136 on the pot, engaged by a nut 137, the other end of scraper being connected to a link on the opposite side of the pot.

Threading the cover web.—After having 40 been supplied with glue by the mechanism just described, the cover web passes to the table 4, where it is received between pressing rollers arranged above and below the upper surface of the table. The upper roller 138 45 is preferably rigid, being a metallic roller, and the lower roller 139 has a resilient surface, as by means of a rubber cover, and the upper roller is held in brackets 140 pivoted to the frame, there being a spring 141 acting to pull the brackets down against adjustable stop screws 142. A handle 143 is provided to move the upper roller when desired. The body web is fed by its feed rollers between the pressing rollers just mentioned until its front edge is slightly in advance of the front edge of the table, and the cover web passes between said rollers with its glued face against the lower face of the body web, and as the material passes between 55 the pressing rollers, they are firmly pressed together, so that the cover web adheres to the material of the body, and all air bubbles, wrinkles, etc., are squeezed out. As will appear, the end of the cover web will be beyond the end of the body web, and with the

body web and cover web in this assembled relation, two cutters pass horizontally transversely of the webs and sever the same simultaneously, one of these cutters being the body web cutter, previously described.

70

When the body web is severed the preceding section thereof (which forms the body blank to be subsequently folded into the shell) has been positioned by the feeding rollers relatively to the cover web, so 75 that its rear edge is spaced from the front edge of the body web, and this space is spanned by the cover web and is such that the cutter disk of the cover web, when it passes across, provides sufficient length of 80 cover web on each side of the cut (between the front edge of the body web and the rear edge of the body blank) to fold over the front end of the body web and the rear end of the preceding body blank. At this time, 85 and while the cover web is moved and before the cutters operate, a slitter or dagger is projected upwardly through the cover web within the space and slits the cover web in line with the score adjacent that small section of the blank which is to be the uppermost of the superposed sections in the completed shell.

In order to control the blank and to space the same as described, devices are provided 90 for gripping the covered blank and moving the same to provide the space referred to. Supported on the standards 79 and 80 is a transverse rock shaft 144 to which is fixed an arm 145 in turn pivoted to one end of a 95 connecting rod 146; the other end of said rod being pivotally connected to a rock arm 147 pivoted on the frame and operated by means of a cam 148 on the shaft 17, a spring 149 connecting the arm 147 and frame to 100 operate the former in one direction. A relatively large pinion 150 is loosely mounted on the rock shaft adjacent one end thereof and meshes with the gear 81 of the upper feed roller shaft. A gear segment 151 of 105 equal diameter with the pinion 150 and concentric therewith is fixed to the rock shaft 144 on one side of the pinion 150, and is in constant mesh with a smaller pinion 152 on a transverse shaft 153 having a similar 110 pinion 154 at its end adjacent the opposite side of the table. The pinions 152 and 154 are designed to constantly mesh with racks 155 mounted on horizontal reciprocating rods 156 supported in guideways formed by shoulders 157 at the sides of the table 4. A ratchet wheel 158 is fastened to the pinion 150 on the side opposite the segment gear 151 and is designed to be operated by a pawl 159 pivoted on an arm 160 fixed to the rock shaft 115 144. A stop pin 161 on the upper portion of the frame is designed to limit the movement of the arm 160 in the feeding direction.

Each of the rods 156 is provided at its outer end with an upright bracket 162 pro- 120 125 130

viding transverse sleeves 163, 164 in which are journaled short shafts 165, 166, each shaft having a preferably curved gripper jaw or finger 167, 168, at its inner end and intermeshing toothed segments 169, 170 at its outer end, these jaws being disposed within the width of the webs; one shaft of each pair of gripper jaws having an arm 171 pivoted to an adjustable connecting rod 172 extending rearwardly and connected to parallel crank arms 173 on a transverse rock shaft 174 journaled on the gripper carrying rods 156, said shaft 174 having an intermediate arm 175 to which is pivoted a threaded rod 176 engaged by a sleeve 177 loose on said rod and adapted to be operated in one direction or the other by cams 178, 179, secured to the shaft 31 through the instrumentality of a rock lever comprising arms 180, 181, 182. The jaws 167, 168, are designed to open or close at proper points in the path of reciprocation of the rods 156, this being accomplished by the movements of the lever 182, and the time of the accomplishment of the operations being determined by the position of the nuts 183 and 184 on the rod 176. Furthermore, it is designed to lock the grippers in closed position in order to accurately retain the blanks 20 while being moved by the grippers, and to this end the cranks 173 are designed to be in alinement with the rods 156 when the grippers are in closed position, so that any movement of the rods 156 under the influence of the pinions 152 will have no tendency to disturb the position of the shaft 174. It will be observed that the rod 172 is curved at one end and extends over the shaft 174 so as to clear the same during its 25 operation.

The operation of feed mechanism for body web.—As the cam 148 rotates, the segment 151 and the arm 160 will be oscillated. The end of the pawl 159 is so disposed relatively 30 to the teeth of the ratchet wheel 158 that after the body web is cut, said pawl will move a short distance before contacting with the adjacent tooth of the ratchet wheel, but the segment 151 being in constant connection with racks 155, through pinions 152 and 154, will move the grippers immediately after the cutting of the body web so that the severed blank which is in the grasp of the grippers will be moved a short distance 35 relatively to the bulk of the web, this distance being measured by the distance the pawl 159 has to move before contacting with the adjacent tooth of the ratchet wheel. After the pawl 159 abuts the tooth of the 40 ratchet wheel, the racks and the pinion 150 move together, so that in the subsequent movement in that direction the severed blank and the body web move together, without the lost motion above referred to. 45 After the body web is intermittently fed

onto the table, a front end portion thereof is adhesively assembled with the cover web and a blank severed from the front end of the body web, whereupon the front end of the cover web is folded over the front edge 70 of the body blank and adhesively attached thereto. After said blank has been severed the grippers previously described move rearwardly and grasp the assembled body blank and body web, and then move forwardly to carry the severed blank to position for further manipulation in the direction of a mandrel, or former, hereinafter described, at the same time feeding the cover web. 80

It will be noted from what has been heretofore described that the assembled body blank and cover web are fed by the grippers a certain distance relatively to the main body web to provide the space hereinbefore referred to, and that thereafter the main body web is advanced simultaneously with the severed blank. The grippers retain and support the thus assembled parts in a proper horizontal plane beyond the front end of the table 4, with that portion of the cover web between the front end of the body web and the rear end of the severed blank approximately over the front end of the table 4. The forward portion of the table 4 is provided with a recess 185, and the slitter hereinbefore referred to plays up and down in the recess. In the present embodiment the slitter comprises a shaft or shank 186 having an enlarged cutting or slitting end 187 flattened longitudinally of the machine and tapering upwardly into a sharp point, the forward and rear edges of the flattened portion being knife edges. When projected against the cover web the point readily penetrates the web without tearing the same, and the knife edges nicely slit the web intermediate the front end of the body web and the rear end of the body blank in line with the score, and preferably up to the edges of 90 the body web and the body blank. The slitter is guided by its shank in the table 4, its lower end being connected to one end of a bell crank lever 188 fulcrumed on the frame, the other end of the bell crank lever 95 being joined by an adjustable rod 189 to a rock lever 190 having an arm 191 disposed to be operated by a cam 192 on the shaft 17. Preferably the cam positively causes the retraction of the slitter, a spring 193 connected to the bell crank and to the frame causing the projection of the slitter when the recessed portion 194 of the cam is opposite the end of the arm 191. 100

The rear edge of the slotted portion of 125 table 4, in which the pressing rollers 138 and 139 lie, forms a cutting edge adapted to co-operate with the body web disk cutter 84, and immediately adjacent this edge and also adjacent the front edge of the 130

table are holding jaws 195 which alternately press the material against the table and release the same, these operations being accomplished by means of connected parallel arms 196, a link 197 and a rock lever 198 operated by a cam 199 on the shaft 14. The time of operation of the jaws 195 relative to the operation of the machine may be accurately determined by setting the adjusting pin 200 against the link 201, which connects the rock lever 198 with the link 197.

Cutter for cover web.—The cutter for the cover web comprises a circular cutting disk 202 rotatably supported in a fork at the end of a lever 203 pivotally supported intermediate its ends on a stud 204 depending from the carriage and resiliently attached to the carriage at its other end by means of a spring 205 secured to the lever and to a pin 206 projecting from the side of the carriage. The lever 203 is guided in a depending fork 207 secured to the bottom of the carriage whereby the cutter 202 is maintained in upright condition. By this construction the cutting disk 202 is supported adjacent the table at each side thereof, and by means of an adjusting screw 208 the disk 202 may be raised and lowered and the tension of the spring adjusted.

30 *Combined folding and pressing head.*—The mechanism for folding the projecting ends of the cover blank over the ends of the body blank is preferably constructed as follows: Combined folding and pressing elements, comprising folding and pressing jaws, are mounted adjacent the front end of the table and are adapted to fold the projecting front end of the cover web over the end of the body web and at the same time 35 fold the projecting rear end of the cover blank over the rear edge of the body blank, the respective webs and blanks being properly positioned for this purpose, as will appear.

40 45 The numeral 209 indicates the lower portion of the combined folding and pressing element or head, comprising a horizontal bar extending transversely of the direction of feed of the webs, and provided with an upper flat surface presenting oppositely disposed lower folding and pressing jaws 210, 211. Movable mounted in a guiding slot 212 in the lower portion of the head is a bar 213 terminating in oppositely projecting upper jaws 214, 215 adapted to cooperate respectively with the lower jaws 210 and 211 in the folding and pressing operations. Preferably the forward lower jaw is extended somewhat beyond the adjacent upper jaw for a purpose to appear. It is designed to first move the folding head upwardly to fold the projecting end of the cover past the adjacent edges of the body material, and then to move the head 50 55 60 65 rearwardly to fold the cover at one side

rearwardly on the adjacent body material, and thereafter to press the folded parts. To this end the head is at times positioned with its upper surface below the surface of the table 4, and the upper and lower jaws 70 are spaced apart so that when moved into the plane of the webs, said material may enter between the jaws.

The lower jaws are supported and operated through the medium of strong adjustable parallel upright rods 216 respectively connected thereto and to the ends of vertically movable rock levers 217 fulcrumed on the frame, the latter being connected by a bar 218 supporting an anti-friction roller 80 219 with which contacts a cam 220 on the shaft 14, the character of the cam being such as to cause the elevation and descent of the combined folding and pressing head at the proper time in the operation of the 85 machine, its descent being assisted by a spring 221 connected to the frame. The upper jaws are movable relatively to the lower jaw, being guided by the slot 212 and having stops attached thereto comprising 90 parallel adjustable rods 222 terminating in heads 223 adapted to contact with relatively fixed lugs 224 on the frame to limit the upward movement of the upper jaws.

95 Springs 225 connect the rods 216 with the lower jaws, their tension being exerted to separate the jaws. In order to provide for movement of the folding and pressing head longitudinally of the machine the uprights 216 are pivotally connected to the 100 rock levers 217, and a relatively strong spring 226 connected to the head and to the frame draws the head rearwardly toward the table 4. In order to cause motion of the jaws in the opposite direction, there is provided a rock shaft 227 supported between adjustable pins 228 on the frame and provided with arms 229 carrying at their ends rollers 230 which contact with the rear faces of the uprights 216. Intermediate its 110 ends the rock shaft 227 is provided with a depending arm 231 provided with an anti-friction roller 232 contacting with a cam 233 on the shaft 14, the latter being adapted to move the head forwardly longitudinally of the machine against the resistance of the spring 226. Preferably the arm 231 is made in sections and comprises a portion 234 pivotally connected to the main arm 231 and carrying an adjustable pin 235 adapted to 115 120 125 contact with a projection 236 on the main arm, whereby the movement of the head may be accomplished and at the same time the longitudinal position of the head adjusted by means of the pin 235.

125 After the feeding grippers have taken hold of the combined cover web and severed body blank, they advance the same to position, spacing the body blank from the body web, as before described, whereupon the cut- 130

ters operate to sever the cover web and a succeeding body blank. In this position a carrier or transferring device comprising a second set of grippers has been moved into 5 position to receive the now completely severed blank from the first set of grippers.

The carrier comprises two pairs of parallel rock arms adapted to move in a vertical plane, the pairs being spaced apart horizontally. Each pair comprises rear arms 237 and front arms 238, the latter being suitably pivoted on the frame member 1. Links 239 pivotally connect the upper ends of the arms 237 and 238 and are extended 10 rearwardly and terminate in a fixed gripper jaw 240. Coöperatively associated with each fixed jaw 240 is a movable gripper jaw 241 pivoted on the respective links 239 and having an arm 242 pivotally joined by an adjustable rod 243 to arms 244 of a rock shaft 245 journaled in a bracket 246 transversely connecting the links 239 of each pair of rock arms. The rear rock arms 237 are carried by a sleeve 247 loosely supported to 15 oscillate on a transverse rock shaft 248, a spring 249 connected to an arm 250 on the sleeve and to the frame, serving to move the rock arms rearwardly or toward the assembly mechanism, previously described.

20 Pinned to the shaft 248 is an arm 251 carrying a roller 252 adapted to contact a cam 253 on the shaft 17, the shape of this cam determining the movements of the rock arms 237 and 238. Rotatably mounted on the shaft 248 is a rock lever comprising complementary arms 254 and 255 adapted to contact cams 256 and 257, respectively, on the shaft 17 to positively move the lever in either direction, said lever comprising a 25 third arm 258 having an opening through which loosely passes a connecting rod 259 pivotally joined to one of the arms 244. The lower portion of the rod 259 is threaded and stop nuts 260 and 261 engage the rod 30 on each side of the arm 258. In order to provide for adjustment of the positions of the arms 237 and 238, the sleeve 247 is provided with an arm 262 carrying an adjusting pin 263 adapted to contact the arm 251. The cams 256 and 257 are designed to positively open and close the gripper jaws 241 of the carrier.

After the carrier has transferred a completed shell blank from the assembly mechanism to the shell blank folding mechanism hereinafter described, it is moved back into position to receive a succeeding blank, the cam 253 being properly designed to place the grippers of the carrier at a rear position 35 such that the feeding gripper mechanism hereinbefore referred to will deposit the body blank and the attached cover web between the gripper jaws of the carrier, which latter jaws will be in open position ready to receive the assembled elements, the movement

of the jaws being effected by the cams 256 and 257. When the assembled elements are received between the jaws of the carrier, the jaws 241 will be operated and close upon the assembled elements and preferably before the feeding grippers release the same. The feeding grippers then move rearwardly to duplicate their preceding operation. When the assembled elements have been moved to position to be received by the carrier, the cutters pass across the machine and sever the body web to provide a succeeding body blank, the cover web being also severed intermediate said body blank and the preceding body blank which is in position to be received by the carrier. Before the cutting thus described is accomplished, however, the combined pressing and folding head moves upwardly against the cover web and presses the cover web slightly upwardly so as to stretch the same over the upper surface of the head, so that the cover web will be drawn taut for the operation of the cutter.

While the assembled body blank and cover web are being moved by the first grippers into position to be received by the carrier and after a space has been formed between the forward end of the body web and the rear end of the severed body blank, the slitter is projected upwardly and shears the cover material in a proper line, as hereinbefore described, the slitter preferably operating while the cover web is moving. The webs and blank now come to rest, and after 40 both the slitting of the cover web and the operation of the transverse cutters, the carrier is moved slightly forward to further space the blank carried thereby from the succeeding material, the forward blank escaping the forward edge of the head to rest upon the extended face of the forward lower jaw 210. The combined pressing and folding head makes a further upward movement and the adjacent sections of the cover web 45 are folded vertically upward against the adjacent edges of the body blanks, the upper and lower jaws being spaced apart at this time. The vertical fold having been accomplished, the folding head is moved rearwardly, thus folding the cover web rearwardly and horizontally over the end of the severed body blank, and at the same time the cam 253 causes the carrier to make a rearward movement in a path substantially 50 parallel to the path of reciprocation of the carrier, which rearward movement is part of an oscillatory movement, thus sliding the blank carried thereby between the forward jaws of the head and causing the upstanding folded cover blank to be folded horizontally forward onto the body blank. With the parts in this position, the uppermost movement of the upper jaws of the head 55 has been reached and is maintained by the

heads 223 contacting with the stops 224. Continued operation of the machine, however, causes the lower jaws to rise and press or squeeze the folded parts just referred to 5 against the upper jaws so as to insure the production of an efficiently glued joint. After the parts have been squeezed in the manner related, the pressure is relieved and the carrier moves forwardly, thus completing 10 the oscillatory movement, to further move, or transfer, the now completed shell blank to devices which fold it into a shell or tube, and the head makes a forward movement to escape the edge of the succeeding 15 blank, whereupon the head then moves downwardly out of the path of the grippers. It will be observed that the top surface of the folding and pressing head takes position in line with the cover cutting disk, and 20 serves as a platen for said disk during the cutting operation.

In order to positively position the rear edge of the forward or shell blank in line with the front jaws of the folding head, a 25 guide or plunger 266 is slidably guided on the frame to move against the blank and positively press the same onto the extension of the forward lower jaw. Movement at proper times is given to the plunger 266 by 30 means of a cam 267 operating a rock arm 268 connected to an arm of a rock lever 269 in turn connected to the plunger. The weight of the plunger is utilized to depress the same, it being raised by the cam 267.

35 In order that a shell having a completely covered edge may be formed, the folding head is of such a character as to fold over the body blank only those portions of the projecting cover at one side of the slit of the cover, leaving projecting unfolded tongues *g*, *g* of the cover, and in the present embodiment the upper jaw is cut away or 40 provided with a recess 270 in that portion between the slit of the cover web and the adjacent edge of said web, this cut away portion being on both the forward and rear 45 side of the head and having sufficient vertical extent to prevent the upper jaw coming into contact with the glue on the scarf at that side of the body. The upper jaws of the head on the side adjacent the small scarfed flanged section of the body web are also cut away as at 271 sufficiently to prevent 50 squeezing the folded cover web immediately adjacent its edge, so as to minimize at this point the squeezing out the glue which might subsequently interfere with the proper production of the shell.

55 After having been taken by the carrier and moved to fold and press the trailing portion of the cover blank, as described, the shell blank is moved forwardly and associated with a former, bar, or mandrel around which it is folded, and its ends connected, thus 60 forming a complete tube or shell. In the

present embodiment the former comprises a fixed horizontal bar 272 of angular and preferably rectangular section, its dimensions corresponding with the inner dimensions of the shell desired. The former has 70 an upwardly extending portion 273 by means of which it is stationarily fastened on the frame of the machine, and it extends longitudinally of the machine and in line with that section of the blank comprised 75 between the scores *c* and *d*. A bracket comprising upstanding guiding arms 274 is securely fastened to the frame of the machine beneath the former, and a blank supporting plate 275, supported by the bracket arms 274 80 is pressed toward the bottom face of the former 272 by means of springs 276 held in recesses in the bracket and operating against guide pins 277 on the plate and at that position of the former corresponding to the position 85 the blank is to assume when operated upon by the shell folding devices. Also supported by the bracket 274 adjacent the upright walls of the former 272, but spaced therefrom on each side thereof and in the 90 path of the blank on the carrier are stops 278 to determine the foremost position of the blank relative to the former. As the carrier moves forwardly the blank is introduced between the plate 275 and the bottom 95 of the former, coming to position against the stops 278, whereupon the carrier grippers release the blank and the same is supported in position by the plate 275. The shell blank is delivered by the blank carrier 100 between the supporting plate 275 and the lower face of the former 272 and extends transversely of the former with its intermediate smaller section registering with the lower face of the former. When in this 105 position it is designed to bend or fold the projecting ends of the shell blank around the former, secure the ends together, fold the projecting portions or tongues of the cover blank around the edges of the shell, and firmly press the folded portions to provide an efficient glued joint as well as give shape to the shell. To this end a folding and pressing mechanism is disposed to move from beneath the former to partially fold 110 and press the shell blank, another folding and pressing mechanism is disposed above the former to operate upon the blank when folded, and a lateral folder operates at proper times upon the blank. While for 115 the purpose of distinguishing between these folders they may be conveniently referred to in terms of their relative position, it is not intended to thereby limit the position of the folders, it being within the purview of 120 the broader aspects of this invention to locate the folders in other positions than those described, as will be obvious. Supported for vertical reciprocation on guide rails 279 of the uprights 274 is a block or head 280, 125

to the upper portion of which, on opposite sides, are pivoted folding and pressing jaws 281 and 282, these jaws being of a length substantially equal to that of the shell to 5 be formed. The construction and operation of each of these jaws is practically the same with one exception, hence the description of one will suffice for that of the other in most particulars. Preferably each jaw 10 comprises a plate having cut-away portions to lighten the same and provided with parallel arms 283 extending from the opposite sides of the pivot and carrying a shaft 284 supporting an intermediate anti-friction roller 15 285. Thin metallic plates 286 engage pins 287 on the head at one end, arms 288 on these plates resting upon the shaft 284. Pins 289 are attached to the head and pass through openings in the plates 286, and a spring 20 rounds the pins 289 between nuts 290 and the plates 286, whereby the pressure of the plates against the shaft 284 may be varied.

One of the folding jaws is provided with an angular folding projection 291 at its 25 outer end for a purpose which will herein-after appear. In the operation of the machine the head 280 moves upwardly and the jaws fold the blank on the intermediate scores and press the sections folded thereby 30 against the lateral faces of the former, the end face 292 of the head operating to press the blank against the lower face of the former, the folding jaw provided with the projection 291 also folding one of the flanged 35 sections over the top of the mandrel at a proper time. In order to provide for these operations and permit the jaws to engage and disengage the former, the head 280 is provided with openings 293 in its bottom 40 portion, in which are located springs 294 and plungers 295 having guiding extensions 296. Pins 297 secured to the head and passing through slots in the plungers serve to retain the plungers in place. The springs 45 294 yieldingly space the head from its support, so that when the head abuts the plate 275 further upward movement of the carrier is permitted. Two of the plungers 295 at equal distances from the central longitudi- 50 nal line of the head are provided. The head 280 is supported by a carrier comprising a supporting rod 298 having a shoulder 299 on which rests a cross bar 300 secured in position by an extension piece 301 threaded on the rod 298 and terminating in a cam face 302, the piece 301 being disposed in an opening in the head 280 opposite slots 303 on each side of the head and in line with the rollers 285. The carrier is reciprocated toward and from 55 the former at proper times, being provided with rack teeth 304 engaged by a segment gear 305 carried by a rock shaft 306 journaled on the frame. A second gear segment 307 is adjustably mounted on the shaft 306 and meshes with a third segment gear 308.

journaled on the frame and having anti-friction contact with a rotary cam 309 carried by shaft 17. The plungers 295 are also fixed to the cross bar 300.

In the operation of the folder just described the rise of the rod 298 elevates the head 280 through the medium of the plungers 295 and the springs 294, the relative position of the head and plungers continuing until the pressing face 292 of the head 70 contacts with the retaining plate 275. Thereafter, the rollers 285, which in the lower position of the head occupied a position near the apex of the cam 302, are pressed outwardly as the carrier moves upwardly, thus turning the folding jaws inwardly so as to fold the blank upwardly against the upright walls of the former. It will be observed that one of the end sections of the blanks is narrower than the other. 75 After the wider sides of the blank have been folded against the former in the manner described the narrower end section is first folded against the top of the former by a separate laterally positioned device, as will 80 85 now appear.

Mounted on one side of the frame 1 and extending longitudinally thereof is a rock shaft 310 provided with an upwardly extending arm 311 to the upper end of which 90 is pivotally connected a folding blade 312 provided with a pin 313 connected by a spring 314 to the frame of the machine. The blade is so positioned relatively to the mandrel 272 that when moved toward and 95 from the same it will fold the adjacent end of the shell blank down upon the upper surface thereof. In order to retain the blade 312 in proper elevated position and to accurately adjust the same, an adjustable link 100 or rock arm 315 is connected thereto and to a bracket 316 on the frame. Thus the arm 311 and the link 315 provide a substantially parallel motion for the blade 312 and the latter is moved toward and from the mandrel to fold the narrower flanged edge of 105 the blank, by means of a rearwardly projecting arm 316' on the shaft 310 from which depends a link 317 pivotally connected to a forked rock arm 318 fulcrumed on a 110 pin 319 projecting from the frame, the end of the link 317 being engaged by a cam 320 on the shaft 17 and properly shaped to give the desired motion to the blade at proper times. 115

The blade 312 having moved forward and having folded the narrower section of the blank upon the upper surface of the former, the folder 291 then folds the wider flanged section of the blank down upon the narrower 120 section, holding the sections together, the blade 312 immediately retreating. The jaws 281 and 282 together with the jaw 291 retain the blank in the folded condition on the former and press the same thereagainst, 125 130

while an upper folding and pressing device moves down onto the superposed flanged sections and folds and presses the projecting portions of the cover against the under side 5 of the shell.

The numeral 321 indicates the upper carrier or carrier head, comprising a block having a centrally recessed portion 322 in its lower face, and cam faces 323 on its opposite sides longitudinally of the machine. 10 A main press head 324 is movably supported in the carrier head by a shank 325 which engages and is guided in the recess 322, a pin 326 on the carrier head engaging a slot in the shank to retain the main press head. 15 A relatively strong spring 327 surrounds the shank of the main press head in the recess 322 and abuts against shoulders on the carrier head and main press head, respectively, and operates to yieldingly space the 20 main press head from the carrier head. An auxiliary press head 328 having a shank 329 is guided in a central opening in the lower face of the main press head and is spaced from said press head by means of a relatively light spring 330, being retained with the main press head by a pin and slot connection, as illustrated. With this construction, when the several heads just mentioned 25 are in their uppermost position where they do not operate upon the blank the main press head is spaced from the carrier head by the spring 327 and the auxiliary press head is spaced from the main press head by the spring 330, the auxiliary press head having guide pins 331 engaging recesses in the main press head. Furthermore, when the heads are lowered to position to operate 30 upon the shell blank the auxiliary press head relatively lightly contacts and presses the superposed parts of the blank together, the continued downward motion of the heads causing a successive compression of the springs 330 and 327 whereby a stronger 35 pressure is applied. As the jaw 291 is retaining the superposed end of the blank in position on the upper face of the mandrel, the auxiliary press head is provided with a suitable cut-away portion 332 to receive said 40 jaw 291. Combined folding and pressing devices are supported to move with the main press head and also to have motion relative thereto, said folding devices comprising levers 333 supported, respectively, on each side 45 of the main press head and each provided with a folding and pressing jaw 334. Each lever intermediate its ends is pivoted upon the ends of supporting levers 335 pivotally fulcrumed upon the main press head, the 50 opposite ends 336 of the supporting levers being disposed in the path of the carrier head 321. The levers 333 at the ends opposite the jaws 334 contact with the cam faces 323 of the carrier head, preferably by 55

means of anti-friction rollers 337. When 65 the heads are in their uppermost position the carrier head is spaced from the main press head by means of the spring 327 to such an extent that the rollers 337 rest on the cam faces 323 and are held thereagainst 70 by means of a spring 338 joining the levers 333, and in this position of the levers the ends of the folding jaws are disposed closely adjacent the ends of the auxiliary press head 75 so that upon the descent of the heads and the relative movement between the main and auxiliary head the ends of the jaws 334 will pass closely adjacent the edges of the body portion of the shell blank in line with the extending tongues of the cover blank, so as 80 to fold the latter vertically downward against the former. When the jaws 334 have descended a sufficient amount to escape the bottom surface of the body blank the carrier head will move downwardly relatively to the press head and the cam faces 85 323 will cause the jaws 334 to move inwardly to fold the tongue against the inside of the body portion of the shell blank, where it will be adhesively attached by the glue on 90 the tongue. This folding having been accomplished, the carrier head contacts with the ends 336 of the supporting levers and its further downward movement will draw the jaws 334 upwardly, the pressing faces 95 339 thereof coöperating with the auxiliary press head to press or squeeze the folded parts and securely attach the body and cover at the edges of the shell. The press head is provided with parallel faces 340 which are 100 extensions of the cam faces 323 and the rollers 337 are guided by these faces during the squeezing operation. The operation of the upper folding and pressing device upon the shell is maintained after the lower folding 105 and pressing device has retreated in order that the glued parts may be pressed together for an appreciable length of time.

In order to operate the upper folding and pressing device the upper end of the carrier 110 head 321 is pivotally connected to an arm 341 of a rock shaft 342 journaled in a fixed part and having another arm 343 operated through a connecting rod 344 joined to a rock lever 345 journaled on the frame at 115 346 and operated by means of a cam 347 on the shaft 17. A link 348 pivotally connected to the frame and to the main press head serves, in connection with the arm 341, to guide the upward and downward movements 120 of the upper folding and pressing device. It will be understood that the jaws 334 are of a width transversely substantially equal to the interior dimensions of the shell.

In order that the jaws 334 may fold the 125 projecting tongue of the cover as above described, the upper face of the mandrel 272 is recessed as at 349, the edges of the shell

blank projecting above these recesses, the mandrel thus providing a platen face on its upper portion for the reception of the upper blank sections of the shell, against 5 which face the blank is pressed.

Strippers.—Playing in a horizontal slot 350 in the former 272 is a stripper device or block, comprising plates 351 closely adjacent the opposite vertical faces of the former 10 and connected to an intermediate cross piece 352 passing through the slot 350. Each of these plates is provided with a shoulder 353 adapted to engage the rear edge of the completed shell and move the same forwardly 15 along the former from folding position. 354, 354 represent arms pivoted to the stripper on each side of the former and connected by parallel arms 355 to a rock shaft 356 operated through an arm 357 and connecting rod 358 by a cam 359 coöperatively 20 engaging a rock arm 360 fulcrumed on the frame.

Pressers.—As the shells are moved from folding position and along the former, the 25 edge of the cover which may extend slightly beyond the wider face of the shell is pressed down against the shell at the angle thereof by means of a pressing mechanism comprising a carriage or rod 361 having a flanged 30 roller 362 at one end and having a rod 363 pivotally connected near the other end, this latter being provided with a plain and a flanged roller. The flanged rollers coöperate with the edge of the former and with the 35 edge of rollers 364 mounted on the former, so that as the boxes pass therewith, the edge of the cover web adjacent the corner of the box will be pressed closely against the adjacent surface of the shell, and should 40 any part protrude slightly it will be folded down around the corner by the flange of the roller. 365 is a link connected to the carriage 361 and to the frame of the machine, and 366 is a spring attached to the link 45 365 at the end of the machine adapted to hold the presser rollers in substantially stationary position while assisting in pressing the same thereon. Pivotally attached to the bar 363 and to a bracket 367 on the frame is 50 a rod 368 surrounded by a coiled spring 369 which exerts its pressure against the carriage.

The shells are moved along the carriage by the stripper, and succeeding shells move 55 those ahead, so that eventually the shells are forced from the stripper to a reduced portion thereof, comprising a pivoted rod 370 having a free end by means of which the completed shells may be directed into a suitable receptacle.

In case the cover web should be wider than required for the shell, or should its disposition relative to the body web locate its edge at too great a distance from the glued

and scarfed edge of the body web, means 65 are provided for trimming such edge of the cover web, severing the same on a predetermined line so that the edge of the trimmed portion will substantially aline 70 with a corner of the shell in folded condition, this edge being the one operated upon by the pressing rollers 362.

371 indicates a fixed shear blade having its cutting edge disposed to cut or trim the cover web in the predetermined line desired. 75 The blade 371 is supported upon a standard 372 mounted on a frame and braced by a rod 373 adjustably mounted in a bracket 374 also fixed to the frame. Coöperating with the fixed shear blade is a rotary shear blade 80 375 having a curved edge and journaled on the standard 372, the axle of the rotary blade having a crank 376 pivotally connected to one end of a bent link 377, the opposite end of said link being connected to 85 a parallel crank 378 journaled in the frame. A mutilated pinion 379 is mounted upon a stud shaft secured to the frame and carries a crank arm 380 pivotally joined to the link 377. The cranks 376, 378 and 380 are parallel, 90 so that when the pinion 379 is rotated, the shear blade 375 is also rotated synchronously therewith. A relatively large mutilated gear 381 is journaled upon the shaft 17 on the frame, its teeth being adapted to mesh 95 with the teeth of the mutilated pinion 379, and the relative number of the teeth of the pinion and gear is such that the pinion makes a complete revolution for something less than half a revolution of the gear; the 100 smooth edges of the pinion and gear conforming for the remainder of a complete revolution of the gear to lock the pinion against rotation and consequently lock the rotary shear blade against movement during such interval.

As the shears operate to sever material which is provided with moist glue, there is a tendency for the severed material to stick to the shear blade and for the glue to dry on 110 said blade. In order to obviate as far as possible such disadvantages, a scraper or clearer comprising an arm 383 is pivoted to a rock lever 384, the latter being pivotally connected by a link 385 to 115 a pin 386 on the mutilated gear 381. As the shear blade 375 comes to rest the arm 383 moves toward the axis of said blade and the lower edge of the scraper is applied to the edge of the blade and held thereagainst 120 by spring 387 upon movement of the arm 384 in the opposite direction, thus scraping off any glue or paper which may have adhered thereto. The arm 384 supports a pipe 388 having a downwardly facing opening 125 389 in line with the edge of the rotary shear blade and from which water is allowed to drip upon the shear blade. This water may

be supplied from a reservoir which is comprised in the cross piece 3 of the main frame, the water being led to the pipe 388 by a suitable flexible tube 390 and controlled by 5 a valve 391.

Should an undue amount of glue accumulate upon the cover web, it may be removed by a scraper bar 392 extending transversely beneath the table 4 adjacent the cover web, 10 and mounted on arms 393 on a shaft 394 provided with a hand lever 395. The bar is held away from the cover web by a spring surrounding the shaft 394 and may be held against the web by a latch rod 396 having a 15 notch 397 adapted to engage a fixed pin 398 on the frame.

Should it be desired to register a particular portion of the length of the cover web with the body web, as for instance 20 when the cover web is provided with printed notices, the feed of the body web may be varied relative to the cover web by adjusting the screw stop pin 399 up or down in a bracket 400, the stop pin serving to limit 25 the upward movement of the arm 145 connected to the gear segment 151.

According to the improved method for making shell blanks and complete shells, the cover web A and the body web B are 30 assembled with the end of one projecting beyond the end of the other a sufficient amount to be folded over the other. Having joined the interfolded ends by means of an adhesive, and having severed a sufficient length from the body web at a point 35 in rear of the folded portions according to the length of shell desired, the severed blank is moved from the web from which it was cut, and in doing so the cover web attached to the blank is also moved. The 40 cover web is then disposed across the space between the blank and the body web and adhesively secured to the body web, the space between the body blank and body 45 web being sufficient, when the cover web is severed intermediate the body blank and body web, to provide a sufficient amount of cover web to fold over the adjacent edges of the body blank and body web. The 50 cover web is then severed intermediate the sections and folded as thus described and adhesively secured to the respective parts of the body. By these operations a completely covered shell blank has been formed 55 which is subsequently folded, on lines longitudinal relative to the webs, into a complete continuous tube or shell, the length of the shell being provided from what may be termed the width of the webs. More particularly the method also involves the slitting of the cover web in line with one of the longitudinal folding lines in the space 60 between the body blank and the body web while moving, and the simultaneous folding 65 of the cover web on the adjacent sections

of the body at one side of the slotted portion, whereby projecting tongues of the cover web remain unfolded and are subsequently folded around the edges of the shell. Several steps involved in the method 70 are illustrated in the diagrammatic views (Figs. 65 to 72).

As the shells are removed from folding position by the stripper they contact a spring finger 401 supported on bracket 274, 75 which presses their lower sections against the mandrel and tends to relieve the superposed sections from the weight of the shell, the spring also acting to retard the movement of the shells and bring them to rest 80 beneath the presser rollers.

A counter 402 is operatively connected by a chain 403 to the stripper arm 357 to record the operations of the stripper and the number of shells produced. 85

Thus by the above described mechanism are accomplished, among others, the objects hereinbefore referred to.

As many changes could be made in carrying out the above method, and in the above 90 construction, and many apparently widely different embodiments of this invention could be made without departing from the scope thereof, it is intended that all matter contained in the above description or shown 95 in the accompanying drawings shall be interpreted as illustrative and not in a limiting sense.

It is also to be understood that the language used in the following claims is intended to cover all of the generic and specific features of the invention herein described and all statements of the scope of the invention, which, as a matter of language, might be said to fall therebetween. 100 105

Having described my invention what I claim as new and desire to secure by Letters Patent is:

1. In an apparatus of the character described, in combination, means adapted to feed a pair of webs, means adapted to successively sever sections from each of said webs, the sections of one web being longer than those of the other, means adapted to superpose the sections of one web on the sections of the other in pairs with the interposition of adhesive and so that the longer blanks overlap the opposite edges of the shorter blanks, means adapted to fold overlapping portions of the longer 110 115 blanks around the adjacent edges of the shorter blanks onto the opposite faces of the latter and adhesively secure the same thereto, and means adapted to successively fold each pair of blanks at an angle to the said interfolded edges and connect the opposite sides thereof.

2. In an apparatus of the character described, in combination, means for feeding a plurality of webs one of which has scores 120 125 130

- extending generally in the direction of feed, means for providing blanks from said webs and securing the blanks together, with the portions of one extending beyond the opposite edges of the other in the general direction of the feeding line, means for slitting the projecting portions adjacent a score of the other blank, means for folding the projecting portions over the opposite edges of the other blank on one side of the slitted portion and securing the same to the other blank, and means for folding the blanks into a shell on lines extending in the general direction of feed.
3. In an apparatus of the character described, in combination, means adapted to feed a body web and a cover web, means adapted to sever said webs transversely into blanks of different lengths, the cover blanks being longer than the body blanks, and to superpose the cover blanks with the body blanks in pairs with the ends of the cover blanks extending in front and in rear of the ends of the body blanks, means adapted to fold the extensions of the cover blanks over the ends of the body blanks onto the opposite faces of the latter and adhesively secure the same thereto, and means adapted to fold the assembled blanks transversely and connect the sides thereof.
4. In an apparatus of the character described, in combination, means adapted to feed a body web and a cover web, means adapted to sever said webs transversely into blanks of different lengths, the cover blanks being longer than the body blanks, and to superpose the cover blanks with the body blanks in pairs with the ends of the cover blanks extending in front and in rear of the ends of the body blanks and one lateral edge of the cover blank outside the adjacent lateral edge of the body blank, means adapted to fold the extensions of the cover blanks over the ends of the body blanks and adhesively secure the same thereto, and means adapted to fold the assembled blanks transversely and connect the sides thereof.
5. In an apparatus of the character described, in combination, means adapted to feed a body web and a cover web, means adapted to sever said webs transversely into blanks of different lengths, the cover blanks being longer than the body blanks and to superpose the cover blanks with the body blanks in pairs with the ends of the cover blanks extending in front and in rear of the ends of the body blanks and one lateral edge of the cover blank outside the adjacent lateral edge of the body blank, and the other lateral edge of the body blank outside the adjacent lateral edge of the cover blank, and means adapted to fold the assembled blanks transversely, superpose the sides of said cover blanks and the sides of said body blanks, and adhesively connect the superposed parts.
6. In an apparatus of the character described, in combination, means adapted to feed a body web and a cover web, means adapted to sever said webs transversely into blanks of different lengths, the cover blanks being longer than the body blanks and to superpose the cover blanks with the body blanks in pairs with the ends of the cover blanks extending in front and in rear of the ends of the body blanks and one lateral edge of the cover blank outside the adjacent lateral edge of the body blank, and the other lateral edge of the body blank outside the adjacent lateral edge of the cover blank, and means adapted to fold the assembled blanks transversely, superpose the sides of said cover blanks and the sides of said body blanks, and adhesively connect the superposed parts.
7. In an apparatus of the character described, in combination, means adapted to feed a body web and a cover web, said body web having scarfed opposite sides, means adapted to sever said webs transversely into blanks of different lengths, the cover blanks being longer than the body blanks, and to superpose the cover blanks with the body blanks in pairs with the ends of the cover blanks extending in front and in rear of the ends of the body blanks and one lateral edge of the cover blank outside the adjacent lateral edge of the body blank, and the other lateral edge of the body blank outside the adjacent lateral edge of the cover blank, and means adapted to fold the assembled blanks transversely, superpose the scarfed sides of said cover blanks and the sides of said body blanks, and adhesively connect the superposed parts.
8. In an apparatus of the character described, in combination, means adapted to feed a body web and a cover web, simultaneously operating cutters adapted to sever said webs transversely into blanks of different lengths, the cover blanks being longer than the body blanks, means adapted to superpose the cover blanks with the body blanks in pairs with the ends of the cover blanks extending in front and in rear of the ends of the body blanks, means adapted to fold the extensions of the cover blanks over the ends of the body blanks and adhesively secure the same thereto, and means adapted to fold the assembled blanks transversely and connect the sides thereof.
9. In an apparatus of the character described, in combination, means adapted to feed a body web and a cover web, means adapted to sever said webs transversely into blanks of different lengths, the cover blanks being longer than the body blanks, and to superpose the cover blanks with the body blanks in pairs with the ends of the cover

blanks extending in front and in rear of the ends of the body blanks, means adapted to provide longitudinal slits in the extensions of the cover blanks in line with a folding line, means adapted to fold the extensions of the cover blanks at one side of said slits over the ends of the body blanks and adhesively secure the same thereto, means adapted to fold the assembled blanks transversely and connect the sides thereof, and means adapted to fold the extensions at the other side of said slits over the edge of the folded blank and adhesively secure the same thereto.

15 10. In an apparatus of the character described, in combination, means adapted to feed a body web and a cover web, means adapted to sever said webs transversely into blanks of different lengths, the cover blanks 20 being longer than the body blanks, and to superpose the cover blanks with the body blanks in pairs with the ends of the cover blanks extending in front and in rear of the ends of the body blanks, one lateral edge of 25 the cover blanks outside the adjacent lateral edge of the body blanks and the other lateral edge of the body blank outside the adjacent lateral edge of the cover blank, means adapted to provide longitudinal slits in the front 30 and rear extensions of the cover blanks in line with a folding line, means adapted to fold the extensions of the cover blanks at one side of said slits over the ends of the body blanks and adhesively secure the same thereto, and means adapted to fold the blanks 35 transversely and superpose the sides of said cover blanks and the sides of said body blanks and adhesively connect said sides.

11. In an apparatus of the character described, in combination, means adapted to support a supply of body web, means adapted to support a supply of cover web, means adapted to intermittently feed said webs, means adapted to guide said webs into superposed relation with a side of the cover web overlapping the side of the body web, means adapted to apply adhesive to that surface of the cover web adjacent the body web, means adapted to apply adhesive to a side of the 40 body web, means adapted to sever said webs transversely into blanks of different lengths, the cover blanks being longer than the body blanks, and to position the body blanks with the cover blanks in pairs with the ends of 45 the cover blanks overlapping the front and the rear ends of the body blanks, means adapted to fold the overlapping front and rear ends of the cover blanks around the ends of the body blanks onto the opposite faces 50 thereof, and means adapted to fold the assembled blanks transversely and overlap the sides of the body blanks.

12. In an apparatus of the character described, in combination, means adapted to 55 feed a body web and a cover web, means

adapted to sever said webs transversely into blanks of different lengths, the cover blanks being longer than the body blanks, and to superpose the cover blanks with the body blanks in pairs with the ends of the cover 70 blanks extending in front and in rear of the ends of the body blanks, means adapted to provide longitudinal slits in the extensions of the cover blanks in line with a folding line, means adapted to fold the extensions of the cover blanks at one side of said slits over the ends of the body blanks and adhesively secure the same thereto, means adapted to fold the assembled blanks transversely and connect the sides thereof, means 80 adapted to fold the extensions at the other side of said slits over the edges of the folded blanks and adhesively secure the same thereto, and means adapted to press the lateral edge of the cover blank in the folded blank. 85

13. In an apparatus of the character described, in combination, means adapted to sever a blank from the front end of a body web and superpose the same on the front end of a cover web in rear of the front edge of 90 the cover web, means adapted to fold a portion of the front end of the cover web around the front end of said blank and adhesively secure the same thereto, means adapted to feed the body web and the assembled blank and cover web and space the rear edge of the blank from the front edge of the body web, means adapted to transversely sever the cover web within said space at a distance from the adjacent edges of said 100 blank and body web, means adapted to fold that portion of the rear edge of the cover blank opposite said first folded portion around the rear edge of the body blank and adhesively secure the same thereto, means 105 adapted to simultaneously fold said assembled blanks transversely and adhesively secure the sides of the body blank together and the sides of the cover blank together, and means adapted to fold unfolded portions of 110 said cover blank around the edges of said folded blank and adhesively secure the same thereto.

14. In an apparatus of the character described, in combination, means adapted to 115 sever a blank from the front end of a body web and superpose the same on the front end of a cover web in rear of the front edge of the cover web, means adapted to fold a portion of the front end of the cover web 120 around the front end of said blank and adhesively secure the same thereto, means adapted to feed the body web and the assembled blank and cover web and space the rear edge of the blank from the front edge 125 of the body web, means adapted to transversely sever the cover web within said space at a distance from the adjacent edges of said blank and body web, means adapted to fold that portion of the rear edge of the cover 130

- blank opposite said first folded portion around the rear edge of the body blank onto the opposite face thereof and adhesively secure the same thereto, means adapted to
- 5 simultaneously fold said assembled blanks transversely and adhesively secure the sides of the body blank together and the sides of the cover blank together, and means adapted to simultaneously fold unfolded portions of
- 10 said cover blank around the edges of said folded blank and adhesively secure the same thereto.
15. In an apparatus of the character described, in combination, means adapted to
- 15 sever a blank from the front end of a body web and superpose the same on the front end of a cover web in rear of the front edge of the cover web, means adapted to fold a portion of the front end of the cover web
- 20 around the front end of said blank and adhesively secure the same thereto, means adapted to feed the body web and the assembled blank and cover web and space the rear edge of the blank from the front edge
- 25 of the body web, means adapted to transversely sever the cover web within said space at a distance from the adjacent edges of said blank and body web, means adapted to fold that portion of the rear edge of the cover
- 30 blank opposite said first folded portion around the rear edge of the body blank onto the opposite face thereof and adhesively secure the same thereto, means adapted to simultaneously fold said assembled blanks
- 35 transversely and adhesively secure the sides of the body blank together and the sides of the cover blank together, and means adapted to fold unfolded portions of said cover blank around the superposed edges of said folded
- 40 blank and adhesively secure the same thereto.
16. In an apparatus of the character described in combination, means adapted to sever a blank from the front end of a body web and superpose the same on the front end of a cover web in rear of the front edge of the cover web, means adapted to fold a portion of the front end of the cover web around the front end of said blank and adhesively
- 45 secure the same thereto, means adapted to
- 50 feed the body web and the assembled blank and cover web and space the rear edge of the blank from the front edge of the body web, means adapted to transversely sever the cover web within said space at a distance
- 55 from the adjacent edges of said blank and body web, means adapted to fold that portion of the rear edge of the cover blank opposite said first folded portion around the rear edge of the body blank onto the opposite face thereof and adhesively secure the same thereto, means adapted to simultaneously fold said assembled blanks transversely and adhesively secure the sides of the body blank together and the sides of the cover blank together, and means adapted to
- 65 simultaneously fold unfolded portions of said cover blank around the superposed edges of said folded blank and adhesively secure the same thereto.
17. In an apparatus of the character described, in combination, means for making a blank provided with oppositely projecting tongues, means for folding the blank into a shell, and means for folding the respective tongues around different edges of the shell.
18. In an apparatus of the character described, in combination, means for making a shell blank comprising a body blank and a cover blank, one of said blanks having oppositely projecting tongues, means for folding the shell blank into a shell, and means for folding the tongues over the opposite edges of the shell.
19. In an apparatus of the character described, in combination, means for making a shell blank, comprising a body blank and a cover blank from a plurality of continuous webs, means for slitting the cover blank adjacent the opposite edges of the body blank, means for folding the cover blank on the body blank at one side of the slit portion thereby leaving unfolded tongues of the cover blank, means for folding the shell blank into a shell, and means for folding the tongues of the cover blank over the opposite edges of the shell.
20. In an apparatus of the character described, in combination, means for making a shell blank comprising a body blank and a cover blank from a plurality of continuous webs, the body web being scored longitudinally, means for slitting the cover blank adjacent the opposite edges of the body blank in line with a score, means for folding the cover blank over the opposite edges of the body blank and adhesively securing the same thereto providing projecting tongues of the cover blank, means for folding the shell blank into a shell, and means for folding the tongues over the opposite edges of the shell and adhesively securing the same thereto.
21. In an apparatus of the character described, in combination, means for making from a plurality of continuous webs successive series of shell blanks, comprising a superposed cover blank and body blank, one of said blanks having portions projecting beyond the opposite edges of the other blank, means for slitting the projecting portions adjacent opposite edges of the other blank, means for folding the oppositely projecting portions over the opposite edges of the other blank, providing oppositely projecting tongues, means for folding the shell blank into a shell, and means for folding the tongues over the opposite edges of the shell.
22. In an apparatus of the character described, in combination, means adapted to

sever a blank from the front end of a body web and superpose the same on the front end of a cover web in rear of the front edge of the cover web, means adapted to fold a portion of the front end of the cover web around the front end of said blank and adhesively secure the same thereto, means adapted to feed the body web and the assembled blank and cover web and space the rear edge of the blank from the front edge of the body web, means adapted to transversely sever the cover web within said space at a distance from the adjacent edges of said blank and body web, and means adapted to fold that portion of the rear edge of the cover blank opposite said first folded portion around the rear edge of the body blank and adhesively secure the same thereto.

23. In an apparatus of the character described, in combination, means adapted to superpose the end of a cover web and a body blank with the interposition of adhesive, means adapted to superpose the end of a body web on said cover web with its front edge spaced from the rear edge of said body blank and with adhesive between said webs, means adapted to sever the cover web between the rear edge of the body blank and the adjacent edge of said body web at a distance from said adjacent edges, and means adapted to simultaneously fold portions of the adjacent sections of the cover web respectively around said spaced edges of the body material and adhesively secure the same thereto.

24. In an apparatus of the character described, in combination, means adapted to superpose the end of a cover web and a body blank with the interposition of adhesive, means adapted to superpose the end of a body web on said cover web with its front edge spaced from the rear edge of said body blank and with adhesive between said webs, means adapted to simultaneously sever the cover web between the rear edge of the body blank and the adjacent edge of said body web at a distance from said adjacent edges, and the body web at a distance in rear of said front edge, and means adapted to simultaneously fold portion of the adjacent sections of the cover web respectively around said spaced edges of said sections.

25. In an apparatus of the character described, in combination, means adapted to longitudinally feed and superpose the end of a cover web and a body blank with the interposition of adhesive, means adapted to superpose the end of a body web on said cover web with its front edge spaced from the rear edge of said body blank and with adhesive between said webs, means adapted to transversely sever the cover web between the rear edge of the body blank and the adjacent edge of said body web at a distance from said adjacent edges, means adapted to

simultaneously longitudinally fold portions of the adjacent sections of the cover web respectively around said spaced edges of the body material and adhesively secure the same thereto, means adapted to fold the assembled blanks transversely and connect the sides thereof, and means adapted to simultaneously fold the remaining unfolded portions of the cover blanks around the respective adjacent edges of the folded blanks and adhesively secure the same thereto.

26. In an apparatus of the character described, in combination, means for providing from a plurality of continuous webs a plurality of blanks, means for gluing and assembling said blanks with the opposite edges of one projecting beyond the opposite edges of the other, means for slitting the projecting portions adjacent the opposite edges of the other, and means for folding the projecting portions at one side of the slit over the adjacent edges of the other blank.

27. In an apparatus of the character described, in combination, means for providing from a plurality of continuous webs, one of which has longitudinal scores, a plurality of blanks, means for gluing and assembling said blanks with the opposite edges of one projecting beyond the opposite edges of the other, means in line with a score of the other for slitting the projecting portions adjacent the opposite edges of the other, and means for folding the projecting portions at one side of the slit over the adjacent edges of the other blank.

28. In an apparatus of the character described, in combination, a plurality of web supplies, means adapted to assemble end portions of the webs with a portion of one projecting beyond the other, means for severing one web at a distance from said end to provide a blank, means to fold the projecting portion over one edge of the blank and secure the same thereto, means to cause relative movement between the assembled elements and the other web to space the severed blank from its web, means to move both webs while maintaining a space between the severed blank and its web, means to sever the other web between the severed blank and its web to provide a portion extending beyond the opposite edge of said severed blank, and means to fold the last mentioned extending portion around said opposite edge and secure the same thereto.

29. In an apparatus of the character described, in combination, a plurality of web supplies, means adapted to successively sever blanks from each web and position a blank of one web relative to a blank of the other so that a portion of said blank extends beyond the edge of said other blank, means adapted to cause the end of one web to extend beyond the edge of a blank immediately succeeding said juxtaposed blanks, and

means adapted to simultaneously fold said extended portions around the adjacent edges of said blanks.

30. In an apparatus of the character described, in combination, a plurality of web supplies, means adapted to assemble the webs with a portion of one extending beyond the other, and means adapted to slit one web at its extended portion and thereby 10 provide a slitted extended portion.

31. In an apparatus of the character described, in combination, a plurality of web supplies, means adapted to sever blanks from each web and position the blanks of 15 one web with a portion extending beyond opposite edges of those of the other, and means adapted to provide a slit in the extended portions.

32. In an apparatus of the character described, in combination, means adapted to feed a cover web, means adapted to feed a body web, sever a section therefrom and dispose said section and the end of the body web on the cover web with the rear edge of 25 the section spaced from the front edge of the body web, and means adapted to longitudinally slit the cover web between said edges.

33. In an apparatus of the character described, in combination, means adapted to feed a cover web, means adapted to feed a body web, sever a section therefrom and dispose said section and the end of the body web on the cover web with the rear edge of 35 the section spaced from the front edge of the body web, and means adapted to longitudinally slit the cover web between said edges while said web is being fed.

34. In an apparatus of the character described, in combination, means adapted to intermittently feed a body web and a cover web, means adapted to sever blanks from each web in succession, means adapted to space the blank of the body web longitudinally from the severed end of the body web, and means adapted to longitudinally slit the body web in said space between successive states of rest of said cover web.

35. In an apparatus of the character described, in combination, means adapted to intermittently feed a body web and a cover web, means adapted to sever blanks from each web in succession, means adapted to space the blank of the body web longitudinally from the severed end of the body web, and means adapted to longitudinally slit the body web in said space between successive states of rest of said cover web and sever the same transversely intermediate the ends 55 of said slit between successive movements of said cover web.

36. In an apparatus of the character described, in combination, body web feeding mechanism, cover web feeding mechanism, 60 means adapted to operate said mechanisms

to feed one web a different amount from the other in the same general direction, means adapted to guide said webs into superposed relation, means adapted to interpose adhesive between said webs when superposed, means adapted to sever a blank from the front end of the body web and secure the same to the end of the cover web to move therewith, a slitter, and means adapted to cause said slitter to pierce said 75 cover web between said blank and its web while said cover web is being fed.

37. In an apparatus of the character described, in combination, a plurality of web supplies, means adapted to assemble the webs with a portion of one extending beyond the other, means adapted to slit the one web at the extended portion, and means adapted to fold the extending portion at one side of the slit around the edge of the other. 80

38. In an apparatus of the character described, in combination, a plurality of web supplies, means adapted to sever blanks from each web and position the blanks of one web with a portion extending beyond opposite 90 edges of those of the other, means adapted to slit the extending portions, and means adapted to fold extending portions at one side of the slits around the adjacent edges of the other blanks. 95

39. In an apparatus of the character described, in combination, a plurality of web supplies, means adapted to sever blanks from each web and position the blanks of one web with a portion extending beyond opposite 100 edges of those of the other, means adapted to slit the extending portions, and means adapted to simultaneously fold extending portions of a plurality of the blanks around the edges of a plurality of the other blanks. 105

40. In an apparatus of the character described, in combination, a plurality of web supplies, means adapted to assemble end portions of the webs with a portion of one projecting beyond the other, means for severing one web at a distance from said end to provide a blank, means to fold the projecting portion over the edge of the blank and secure the same thereto, means to cause relative movement between the assembled elements and the other web to space the severed blank from its web, and means adapted to slit the web at a point between the severed blank and its web. 115

41. In an apparatus of the character described, in combination, a plurality of web supplies, means adapted to assemble end portions of the webs with a portion of one projecting beyond the other, means for severing one web at a distance from said end to provide a blank, means to fold a projecting portion over the edge of the blank and secure the same thereto, means to cause relative movement between the assembled elements and the other web to space the severed blank 125 130

from its web, comprising means to move the web, and means adapted to slit the web at a point between the severed blank and its web during its movement.

42. In an apparatus of the character described, in combination, a plurality of web supplies, means adapted to assemble end portions of the webs, with a portion of one projecting beyond the other, means adapted to 10 fold the projecting portion onto the other and secure the same thereto, means adapted to sever the webs when assembled so as to provide a portion of one severed section projecting beyond the other section at a distance from said folded portion, and means adapted to fold the last mentioned projecting portion onto the opposite face of the other section and secure the same thereto.

43. In an apparatus of the character described, in combination, a plurality of web supplies, means adapted to assemble the ends of the webs, with a portion of one projecting beyond the other, means adapted to fold the projecting portion onto the other and secure the same thereto, means adapted to sever the webs respectively, at unequal distances from the folded portion, and means adapted to fold one of the last severed portions onto the opposite face of the other and 30 secure the same thereto.

44. In an apparatus of the character described, in combination, a plurality of web supplies, means to feed the webs, means adapted to sever blanks from the webs, 35 means adapted to secure the blanks together at one end, and means adapted to secure the blanks together at the opposite end comprising means to feed the blanks in a direction different to that of the feed of the webs.

45. In an apparatus of the character described, in combination, a plurality of web supplies, means adapted to assemble end portions of the webs with a portion of one projecting beyond the other, means for severing one web at a distance from said end to provide a blank, means to fold the projecting portion over the edge of the blank and secure the same thereto, means to cause relative movement between the assembled ele- 45

50 ments and the other web to space the severed blank from its web, means to move the webs forwardly while maintaining a space between the severed blank and its web, means to sever the other web between the severed 55 blank and its web to provide a portion extending rearwardly of the severed blank, and means to fold the rearwardly extending portion onto the said blank and secure the same thereto comprising means for moving 60 the assembled blanks rearwardly.

46. In an apparatus of the character described, in combination, a support, roller means positioned relatively thereto adapted to feed a web, a rod, grippers carried by the 65 rod, a gear, means to oscillate said gear, con-

nections between said gear and rod adapted to reciprocate the rod, and connections between said gear and roller means adapted to rotate the latter.

47. In an apparatus of the character described, in combination, a support, web feeding rollers having intermeshing pinions, a rod comprising a rack and a gripper adapted to grip a second web, a rock shaft, a gear fixed to said shaft, a pinion meshing with 75 said gear and said rack, a gear wheel loosely mounted on the rock shaft and engaging a roller pinion and comprising a ratchet wheel, a pawl movable with the rock shaft and co-operating with the ratchet wheel, and means 80 to oscillate the rock shaft.

48. In an apparatus of the character described, in combination, a support, web feeding rollers having driving pinions, a rod having a rack and a gripper adapted to grip 85 a second web, a gear, a pinion meshing with said gear and said rack, a gear wheel concentric with said gear and engaging a roller pinion, a ratchet wheel fast to the gear wheel, a pawl fast to the gear and adapted 90 to drive the gear wheel, and means to oscillate said gear.

49. In an apparatus of the character described, in combination, a support, web feeding rollers having driving pinions, a rod 95 having a rack and a gripper adapted to grip a second web, a gear, a pinion meshing with said gear and said rack, a gear wheel concentric with said gear and engaging a roller pinion, a ratchet wheel fast to the gear 100 wheel, a pawl fast to the gear and adapted to drive the gear wheel, means to oscillate said gear, and a stop to limit the stroke of the pawl in one direction.

50. In an apparatus of the character described, in combination, means adapted to supply a plurality of continuous webs, means adapted to divide the webs into blanks and assemble the blanks, and means adapted to transfer the blanks from assembly position 105 comprising a plurality of reciprocatory gripper mechanisms, and means adapted to transfer the blanks from one gripper mechanism 110 to the other.

51. In an apparatus of the character described, in combination, a glue supply roller, means adapted to feed a web past the supply roller, a pinion fixed to the supply roller, a dauber comprising a glue applying roller adapted to receive glue from the supply 115 roller, a pinion connected to the applying roller, means to move the applying roller back and forth between the web and the supply roller, means to cause the pinions of the supply roller and the applying roller to mesh when the applying roller is receiving glue from the supply roller, and means to disengage the pinions when the applying roller is applying glue to the web.

52. In an apparatus of the character de- 130

- scribed, in combination, parallel rock shafts, parallel cranks mounted thereon, a dauber rotatably mounted on said cranks and having a gear wheel, a glue supply roller, a gear wheel carried thereby, and means to simultaneously oscillate the rock shafts to simultaneously move the dauber and its gear into or out of engagement with the supply roller and its gear. 5
53. In an apparatus of the character described, in combination, parallel rock shafts, parallel cranks mounted thereon, a dauber rotatably mounted on said cranks and having a gear wheel, a glue supply roller, a gear wheel carried thereby, gears on the rock shafts, a gear meshing with the rock shaft gears, a belt pulley fast to the latter gear, a cam, a rock lever adapted to be oscillated thereby, and means comprising a resilient belt engaging the pulley and attached to the rock lever and the frame, respectively. 10
54. In an apparatus of the character described, in combination, means to intermittently feed a web, a glue supply roller, a glue applying roller, means adapted to move the applying roller to apply glue to the web at a point spaced from the edge of the web and yieldingly press the roller against the web as the web is fed, and means adapted to move the applying roller into contact with the supply roller and positively rotate the applying roller between the intervals of motion of the web. 15
55. In an apparatus of the character described, in combination, a combined folding and pressing head comprising a bar providing a jaw, a second bar guided in the first and providing a second jaw co-operatively associated with the first, connections between the jaws adapted to yieldingly move one jaw from the other, means to simultaneously move the jaws, and means to cause relative movement between the jaws. 20
56. In an apparatus of the character described, in combination, a combined folding and pressing head comprising a bar providing oppositely projecting jaws, a second bar guided in the first and providing oppositely projecting jaws adapted to co-operate with the first jaws, connections adapted to space the oppositely projecting jaws of one bar from those of the other, means to simultaneously move the jaws and means to cause relative movement between the jaws of the bars. 25
57. In an apparatus of the character described, in combination, a jaw, a second jaw, a spring connecting the jaws and adapted to move them apart, a rock lever, a rod joining the lever and one jaw, a cam adapted to operate the rock lever, and a stop adapted to limit the movement of the other jaw. 30
58. In an apparatus of the character described, in combination, a table, a folding and pressing head adjacent thereto comprising an upper jaw, a lower jaw, a spring con-
- necting the jaws whereby movement of one is imparted to the other, a cam and connections adapted to raise and lower the jaws, means to limit the uppermost movement of the upper jaw, a rock shaft, arms thereon adapted to contact the head, and a cam and connections adapted to cause the arms to move the head at an angle to the first mentioned movement. 35
59. In an apparatus of the character described, in combination, a carrier comprising a gripper, means adapted to reciprocate the carrier, means adapted to open and close the gripper, and means adapted to oscillate the gripper in a path substantially parallel to its path of reciprocation during its reciprocation. 40
60. In an apparatus of the character described, in combination, a carrier comprising a gripper, means adapted to reciprocate the carrier, means adapted to oscillate the gripper between the ends of its reciprocatory path during its reciprocation, and means adapted to open the gripper at one end of the path of reciprocation and close the same at the other. 45
61. In an apparatus of the character described, in combination, a carrier comprising a gripper, means adapted to reciprocate the carrier, means adapted to oscillate the gripper in a path substantially parallel to its path of reciprocation during its reciprocation, and means adapted to open the gripper at one end of the path of reciprocation and close the same at the other and hold it closed during the oscillatory movement. 50
62. In an apparatus of the character described, in combination, pairs of parallel rock arms spaced apart, rods pivotally connecting the arms of each pair and providing relatively fixed gripper jaws, relatively movable co-operating gripper jaws carried by said rods, a rotary shaft, cams thereon, and means whereby the cams impart reciprocatory movements to said arms and the movable jaws. 55
63. In an apparatus of the character described, in combination, a carrier comprising a gripper, a rotary shaft, cam means on the shaft, and means whereby upon rotation of the shaft the carrier is reciprocated and the gripper oscillated between the ends of and in a path substantially parallel to its reciprocatory path, and the gripper is opened at one end of the reciprocatory path and closed at the other. 60
64. In an apparatus of the character described, in combination, a fixed horizontal former angular in cross section, a vertically disposed bracket supported adjacent the former, a relatively stationary blank supporting plate guided in the bracket, spring means adapted to press the plate toward the former, and a stop spaced from the former and disposed transversely of the line of engagement between the former and plate. 65

65. In an apparatus of the character described, in combination, a carrier comprising a cam, a folder movable with the carrier, and means whereby relative movement between the carrier and folder causes the folder to move under the influence of the cam.

66. In an apparatus of the character described, in combination, a mandrel, a carrier, folding jaws mounted on the carrier, means to move the carrier toward and from the mandrel, and means whereby the movement of the carrier causes the jaws to move toward and from each other independently of the mandrel.

67. In an apparatus of the character described, in combination, a movable support comprising a cam, a head yieldingly mounted on the support, a stationary mandrel, folding jaws pivoted on the head and comprising portions adapted to contact the cam, and spring means on the head disposed to press said jaw portions against the cam.

68. In an apparatus of the character described, in combination, a movable support comprising a cam, a stationary mandrel, pivoted folding jaws movable relative to the cam, and means whereby relative movement of the cam and jaws causes the jaws to move toward and from each other and relative to said mandrel.

69. In an apparatus of the character described, in combination, a stationary rectangular mandrel, a head adapted to move toward and from one face of the mandrel, jaws carried by the head adapted to move in an arcuate path toward and from opposite sides of the mandrel, and means to move the head toward and from the mandrel and simultaneously move the jaws toward and from the same.

70. In an apparatus of the character described, in combination, a supporting rod having an end provided with a cam face, a head having a recess in which the end of the rod rests, and provided with slots on opposite sides of the rod, pivoted folding jaws on the head, comprising arms having anti-frictional contact with the cam through the slots, means comprising springs supported on the head and disposed to press the arms against the rod, openings in the head on opposite sides of the rod, plungers connected to the rod and disposed in the openings, springs between the plungers and the head and adapted to yieldingly support the head on the rod, a mandrel, and means to move the head toward and from the mandrel.

71. In an apparatus of the character described, in combination, a reciprocatory support, a head carried thereby and adapted to permit the support to move relatively thereto in the line of reciprocation, oppositely disposed folding jaws journaled on the head, and means on the support adapted to cause

said jaws to move toward and from each other as the support is operated.

72. In an apparatus of the character described, in combination, a reciprocatory support, a head carried thereby and adapted to permit the support to move relatively thereto in the line of reciprocation, oppositely disposed folding jaws journaled on the head, each jaw having an arm and means comprising oppositely disposed cam faces on the support adapted to contact said arms as the support reciprocates.

73. In an apparatus of the character described, in combination, a reciprocatory support, a head carried thereby and adapted to permit the support to move relatively thereto in the line of reciprocation, oppositely disposed folding jaws journaled on the head, each jaw having an arm and means comprising oppositely disposed cam faces on the support adapted to contact said arms as the support reciprocates, and means adapted to yieldingly press said arms toward said cam faces.

74. In an apparatus of the character described, in combination, a reciprocatory support comprising parallel plungers, a head having guide openings in which the plungers are received, springs interposed between said plungers and said head, oppositely disposed folding jaws journaled on said head, and a member having oppositely disposed cam faces adapted to cause said jaws to move toward and from each other as the support is operated.

75. In an apparatus of the character described, in combination, a reciprocatory support comprising parallel plungers and a rod having oppositely disposed cam faces, a head having guide openings to receive said plungers and said rod, and having slots opposite said rod, springs adapted to yieldingly space said head from said support, oppositely disposed folding jaws journaled on said head, each jaw having a portion adapted to contact said rod through said slots.

76. In an apparatus of the character described, in combination, a bracket comprising longitudinal guides, a head adapted to reciprocate on said guides, a blank supporting plate longitudinally movable on said bracket in the path of said head, oppositely disposed folding jaws journaled on said head and a reciprocatory support on which said head is yieldingly supported comprising means adapted to move said jaws toward and from each other as the support reciprocates.

77. In an apparatus of the character described, in combination, a stationary mandrel, a support adapted to reciprocate toward and from the mandrel, a head carried by the support and adapted to permit the support to move relatively thereto in the line of reciprocation, oppositely disposed folding

5 jaws mounted on the head to move in arcuate paths, and means on the support adapted to cause said jaws to move toward opposite sides of the mandrel as the support is reciprocated.

78. In an apparatus of the character described, in combination, a stationary mandrel, a press head adapted to move toward and from the same, folding jaws on said head, means adapted to space said head from the mandrel and the jaws from opposite sides of the mandrel when the head is so spaced, means adapted to move a blank into the space so formed, means adapted to move 10 said head and cause the blank to be pressed against said mandrel, and means whereby the mandrel causes said jaws to move toward opposite sides thereof and fold the blank thereagainst.

20 79. In an apparatus of the character described, in combination, a stationary mandrel, a press head adapted to move toward and from the same, folding jaws on said head, means adapted to space said head from the mandrel and the jaws from opposite sides of the mandrel when the head is so spaced, means adapted to move a blank into the space so formed, means adapted to move 25 said head and cause the blank to be pressed against said mandrel, and means whereby the pressure between the blank and mandrel causes said jaws to move toward opposite sides thereof and fold and press the blank thereagainst.

30 80. In an apparatus of the character described, in combination, a stationary mandrel, a press head adapted to move toward and from the same, folding jaws on said head, means adapted to space said head from the mandrel and the jaws from opposite sides of the mandrel when the head is so spaced, means adapted to move a blank into the space so formed, means adapted to move 35 said head and cause the blank to be pressed against said mandrel, and means whereby the mandrel causes said jaws to move toward opposite sides thereof and fold the projecting portions of said blank against opposite sides of the mandrel and one projecting portion against the side opposite said head.

40 81. In an apparatus of the character described, in combination, a stationary mandrel, a press head adapted to move toward and from the same, folding jaws on said head, means adapted to space said head from the mandrel and the jaws from opposite sides of the mandrel when the head is so spaced, means adapted to move a blank into the space so formed, means adapted to move 45 said head and cause the blank to be pressed against said mandrel, and means whereby the mandrel causes said jaws to move toward opposite sides thereof and fold the projecting portions of said blank against opposite

sides of the mandrel and one projecting portion against the side opposite said head, and a reciprocatory blade adapted to fold the oppositely projecting portion against said first folded projecting portion. 70

82. In an apparatus of the character described, in combination, a stationary former, means to feed blanks to position adjacent the former comprising rock arms provided with grippers, and means to fold the blanks 75 around the former comprising a movable support, a cam thereon, pivoted folding jaws movable relative to the cam, means to move the support toward and from the former, and means whereby the movement 80 of the support toward and from the former causes the folding jaws to fold the blank around the former and to release the same.

83. In an apparatus of the character described, in combination, a stationary former, 85 means to feed blanks to position adjacent the former comprising rock arms provided with grippers, and means to fold the blanks around the former comprising a movable support, a cam thereon, pivoted folding jaws 90 movable relative to the cam, means to move the support toward and from the former, and means whereby the movement of the support toward and from the former causes the folding jaws to fold the blank around the 95 former and press the same thereagainst and to release the same.

84. In an apparatus of the character described, in combination, a stationary former, means to feed blanks to position adjacent 100 the former comprising pairs of parallel rock arms on opposite sides of the former, and grippers carried by each pair, operating mechanism for the grippers supported by the rock arms, a spring supported plate adjacent the former adapted to support the blank received from the grippers, means operating at an angle to the path of the blank adapted to fold the blank around the former comprising a movable support, a cam thereon, pivoted folding jaws movable relative 105 to the cam, means to move the support toward and from the former, and means whereby the movement of the support causes the folding jaws to fold the blank around 110 the former, and adhesively secure the folded parts together.

85. In an apparatus of the character described, in combination, a mandrel, reciprocating supports on opposite sides thereof, a 129 head carried by each support and adapted to permit the supports to move relatively thereto, respectively, in the line of reciprocation, pairs of folding jaws movably mounted on each head, respectively, and means on 125 each support adapted to cause the jaws of each pair to move toward and from each other as said supports are moved toward and from said mandrel.

86. In an apparatus of the character de- 130

scribed, in combination, a mandrel, means adapted to fold around said mandrel a blank having a body portion and oppositely projecting cover portions, and means adapted to fold said cover portions around the adjacent edges of the body portion and against the opposite face thereof.

87. In an apparatus of the character described, in combination, a mandrel, means adapted to fold around said mandrel a blank having a body portion and oppositely projecting cover portions and superpose the ends of the body portion, and means adapted to fold said cover portions around the adjacent edges of the superposed portion and against the opposite face thereof.

88. In an apparatus of the character described, in combination, a mandrel comprising a platen, reciprocatory press heads on opposite sides of said platen, a pair of folding jaws carried by each head, means adapted to move one head toward said mandrel and cause its jaws to move transversely toward and from opposite sides of said mandrel and the other head to move toward said mandrel and cause its jaws to pass the opposite transverse edges of the platen, then move toward each other and subsequently toward the head on which they are mounted.

89. In an apparatus of the character described, in combination, a stationary mandrel, means adapted to fold a blank therearound, and means comprising angular folding and pressing jaws adapted to move both transversely and longitudinally of said mandrel.

90. In an apparatus of the character described, in combination, a stationary mandrel, means adapted to fold a blank therearound, and means comprising angular folding and pressing jaws adapted to move both transversely and longitudinally of said mandrel in planes at right angles to those of the first mentioned jaws.

91. In an apparatus of the character described, in combination, a mandrel, a horizontally disposed folding blade adapted to move toward and from the mandrel, a rock shaft, an arm on the shaft pivotally connected to the blade, a link pivotally connected to the blade between its end and the point of connection of the arm therewith, a second arm on the rock shaft, a cam, and a second link pivoted to the second arm, and disposed to contact the cam.

92. In an apparatus of the character described, in combination, a carrier head, means to reciprocate the same, a press head supported by the carrier head, means yieldingly spacing the carrier head from the press head, folding devices on the press head, a platen adapted to support a blank, and means whereby the movement of the carrier head causes the press head to press the blank, and relative movement of the

press head and carrier head to operate the folding devices.

93. In an apparatus of the character described, in combination, a carrier head, a press head supported by the carrier head and having a cam face, means yieldingly spacing the carrier head from the press head, a folding device pivoted on the press head and having an arm adapted to contact the cam face of the carrier head, a platen adapted to support a blank, means to move the press head to press the blank, and means to move the carrier head relatively to the press head, whereby the folding device is operated.

94. In an apparatus of the character described, in combination, a carrier head, means to reciprocate the same, a press head supported by the carrier head, means yieldingly spacing the heads, a combined folding and pressing device on the press head, a platen adapted to support a blank, and means whereby the movement of the carrier head causes the press head to press the blank, and relative movement of the press head and the carrier head to fold the blank and press the folded part.

95. In an apparatus of the character described, in combination, a stationary platen adapted to support a blank, a movable carrier, a presser supported thereby, and means whereby movement of the carrier causes the presser to press the blank toward the carrier.

96. In an apparatus of the character described, in combination, a stationary platen adapted to support a blank, a movable carrier, a combined folder and presser supported by the carrier, and means whereby movement of the carrier causes the folder and presser to fold the blank and press the folded part toward the carrier.

97. In an apparatus of the character described, in combination, a platen adapted to support a blank, a movable carrier, a press head supported by the carrier and movable relative thereto, a combined folder and presser supported by the carrier, and means whereby relative movement between the carrier and press head causes the folder and presser to fold the blank and press the folded part against the press head.

98. In an apparatus of the character described, in combination, a carrier head, a relatively movable press head, a spring interposed between the heads and adapted to space the same, a cam on the carrier head, a lever on the press head having a portion in the path of the carrier head, a folder pivoted to said lever and provided with a roller, and means to yieldingly hold the roller against the cam.

99. In an apparatus of the character described, in combination, a carrier head, a relatively movable main press head, the car-

- rier head having a recess, and the press head a shank guided in the recess, a spring encircling the shank and spacing the heads, an auxiliary press head guided in the main 5 press head, a spring spacing the auxiliary and the main press head, pin and slot connections between the main and auxiliary press heads and the carrier head and the main press head, a cam on the carrier head, 10 a lever fulcrumed intermediate its ends on the main press head, one end being disposed in the path of the carrier head, a second lever fulcrumed intermediate its ends on the first mentioned lever, and provided at one 15 end with a folding and pressing jaw, and at the other end with an anti-friction roller, and a spring adapted to hold the roller against the cam.

100. In an apparatus of the character described, in combination, a platen adapted to support a blank, comprising a body portion and a projecting cover portion, a folding device having a pressing face, a press head, means to move the press head against the 25 blank, and means to operate the folding device to fold the projecting portion around the edge of the body portion and press the same thereagainst.

101. In an apparatus of the character described, in combination, a press head, a combined folder and presser movably connected thereto, means to stationarily support a blank, means to move the head toward the blank, and means whereby upon contact of 35 the head and blank the folder and presser are operated to fold the blank at its edge and press the folder part against the blank in a direction opposed to the movement of the head.

102. In an apparatus of the character described, in combination, a fixed horizontal mandrel, means adapted to feed a blank comprising a body and a cover having oppositely projecting portions into position 45 adjacent the mandrel, mechanism adapted to fold the blank around the mandrel, means adapted to hold the blank in said folded condition, mechanism adapted to fold the projecting portions around the edges of the 50 folded blank, and mechanism adapted to remove the shell from folding position.

103. In an apparatus of the character described, in combination, a horizontal mandrel angular in cross section, means adapted 55 to fold a blank comprising a projecting cover portion around the mandrel, and superpose the edge of the projecting portion on the blank at an angle of the mandrel, and means adapted to press the edge of the 60 projecting portion onto the folded blank.

104. In an apparatus of the character described, in combination, a horizontal mandrel angular in cross section, means adapted to fold a blank comprising a projecting 65 cover portion around the mandrel, and su-

perpose the edge of the projecting portion on the blank at an angle of the mandrel, and means adapted to fold and press the edge of the projecting portion onto the folded blank.

105. In an apparatus of the character described, in combination, means adapted to superpose blanks with a portion of one projecting beyond the edge of another, means adapted to fold the projecting portion of one over the other comprising relatively movable jaws, and means adapted to guide the blanks to position between the jaws comprising a movable plunger. 70

106. In an apparatus of the character described, in combination, a source of cover web supply, a source of body web supply, a table on which said webs are adapted to move, means adapted to successively sever said body web transversely and adhesively 80 85 secure the blank to the cover web, means adapted to fold successive front portions of the cover web around the front ends of successive body blanks, respectively, and adhesively secure the folded parts, means 90 adapted to advance the successive assembled body blanks and cover web, and the body web, means adapted to slit the cover web longitudinally so as to dispose the slit between the severed edges of the body web, 95 means adapted to sever the cover web transversely of said slit intermediate its ends, and means adapted to fold rear portions of successive cover blanks around the rear ends of the body blanks and adhesively secure 100 said folded parts together.

107. In an apparatus of the character described, in combination, a source of cover web supply, a source of body web supply, said body web having parallel longitudinal 105 scores in line with lines on which body web blanks are to be folded, a table on which said webs are adapted to move, a transverse rock shaft, curved guide fingers carried thereby and adapted to enter said 110 scores, respectively, bearings in which said shaft is mounted, means adapted to positively adjust said shaft transversely of said web in one direction, a spring adapted to move said shaft in the opposite direction, 115 means adapted to successively sever said body web transversely and adhesively secure the blank to the cover web, means adapted to fold successive front portions of the cover web around the front ends of 120 successive body blanks, respectively, and adhesively secure the folded parts, means adapted to advance the successive assembled body blanks and cover web, and the body web, means adapted to slit the cover web 125 longitudinally so as to dispose the slit between the severed edges of the body web, means adapted to sever the cover web transversely of said slit intermediate its ends, and means adapted to fold rear portions 130

of successive cover blanks around the rear ends of the body blanks and adhesively secure said folded parts together.

108. In an apparatus of the character described, in combination, a source of cover web supply, a source of body web supply, said body web having parallel longitudinal scores in line with lines on which body web blanks are to be folded and having its opposite sides beveled on one face thereof, means adapted to apply a line of glue to one beveled side of the body web inside the edge of said web, a spreader comprising an outwardly and forwardly inclined surface adapted to spread said glue toward the adjacent edge of the body web as the web moves, a table on which said webs are adapted to move, a transverse rock shaft, curved guide fingers carried thereby and adapted to enter said scores, respectively, bearings in which said shaft is mounted, means adapted to positively adjust said shaft transversely of said web in one direction, a spring adapted to move said shaft in the opposite direction, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web, means adapted to slit the cover web longitudinally so as to dispose the slit between the severed edges of the body web, means adapted to sever the cover web transversely of said slit intermediate its ends, and means adapted to fold rear portions of successive cover blanks around the rear ends of the body blanks and adhesively secure said folded parts together.

109. In an apparatus of the character described, in combination, a source of cover web supply, a source of body web supply, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web, means adapted to slit the cover web longitudinally so as to dispose the slit between the severed edges of the body web, means adapted to sever the cover web transversely of said slit intermediate its ends, means adapted to tauten said cover web as it is being severed, and means adapted to fold rear portions of successive cover blanks around the rear ends of the body blanks and adhesively secure said folded parts together.

110. In an apparatus of the character described, in combination, a source of cover web supply, a source of body web supply, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web, means adapted to slit the cover web longitudinally so as to dispose the slit between the severed edges of the body web, means adapted to sever the cover web transversely of said slit intermediate its ends, comprising a transversely movable yieldingly mounted cutting disk, and means adapted to fold rear portions of successive cover blanks around the rear ends of the body blanks and adhesively secure said folded parts together.

111. In an apparatus of the character described, in combination, a source of cover web supply, a source of body web supply, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web comprising web gripping fingers, body web gripping rollers, means adapted to reciprocate said fingers to grasp and move the cover web and body blank relatively to the body web, means to operate said rollers to cause the feed of the body web after the body blank has been moved relatively thereto, means to cause the body web and the blank severed therefrom to move equal amounts after said relative movement, means adapted to slit the cover web longitudinally so as to dispose the slit between the severed edges of the body web, means adapted to sever the cover web transversely of said slit intermediate its ends, and means adapted to fold rear portions of successive cover blanks around the rear ends of the body blanks and adhesively secure said folded parts together.

112. In an apparatus of the character described, in combination, a source of cover web supply, a source of body web supply, a table on which said webs are adapted to move, means adapted to successively sever said body web transversely and adhesively secure the blank to the cover web, means adapted to fold successive front portions of the cover web around the front ends of suc-

cessive body blanks, respectively, and adhesively secure the folded parts, means adapted to advance the successive assembled body blanks and cover web, and the body web, comprising web gripping fingers, body web gripping rollers, means adapted to reciprocate said fingers to grasp and move the cover web and body blank comprising a rock shaft, a pinion loosely mounted thereon, a ratchet adapted to turn with said pinion, a gear fixed to said shaft, a pawl mounted on said shaft and adapted to coöperate with said ratchet, a rack carrying said fingers, a pinion in mesh with said gear and said rack, means adapted to oscillate said shaft, means adapted to operate said rollers to cause the feed of the body web comprising a pinion on a body web roller shaft meshing with the pinion on said rock shaft, means adapted to slit the cover web longitudinally so as to dispose the slit between the severed edges of the body web, means adapted to sever the cover web transversely of said slit intermediate its ends, and means adapted to fold rear portions of successive cover blanks around the rear ends of the body blanks and adhesively secure said folded parts together.

115. In an apparatus of the character described, in combination, a source of cover web supply, a source of body web supply, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, comprising a folding and pressing jaw movable transversely of the table, means adapted to advance the successive assembled body blanks and cover web, and the body web, means adapted to slit the cover web longitudinally so as to dispose the slit between the severed edges of the body web, means adapted to sever the cover web transversely of said slit intermediate its ends, and means adapted to fold rear portions of successive cover blanks around the rear ends of the body blanks and adhesively secure said folded parts together.

113. In an apparatus of the character de-
scribed, in combination, a source of cover
web supply, a source of body web supply, a
table on which said webs are adapted to
move, means adapted to successively sever
said body web transversely and adhesively
35 secure the blank to the cover web, means
adapted to fold successive front portions of
the cover web around the front ends of suc-
cessive body blanks, respectively, and adhe-
sively secure the folded parts, means adapted
40 to advance the successive assembled body
blanks and cover web, and the body web dif-
ferent amounts, comprising fingers adapted
to grip the cover web, rollers adapted to grip
the body web, means to reciprocate said fin-
45 gers and cause the same to grasp and move
the cover web and its attached blank, means
comprising a lost motion device adapted to
first permit relative movement of the cover
web and body web and then cause their si-
50 multaneous movement, means adapted to slit
the cover web longitudinally so as to dis-
pose the slit between the severed edges of
the body web, means adapted to sever the
cover web transversely of said slit interme-
55 diate its ends, and means adapted to fold
rear portions of successive cover blanks
around the rear ends of the body blanks and
adhesively secure said folded parts together.

to fold rear portions of successive cover blanks around the rear ends of the body blanks and adhesively secure said folded parts together.

117. In an apparatus of the character described, in combination, a source of cover web supply, a source of body web supply, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, comprising a bar providing a jaw, a second bar guided in the first and providing a second jaw co-operatively associated with the first, connections between the jaws adapted to yieldingly move one jaw from the other, means to simultaneously move said jaws, means adapted to cause relative movement therebetween, means adapted to advance the successive assembled body blanks and cover web, and the body web, means adapted to slit the cover web longitudinally so as to dispose the slit between the severed edges of the body web, means adapted to sever the cover web transversely of said slit intermediate its ends, and means adapted to fold rear portions of successive cover blanks around the rear ends of the body blanks and adhesively secure said folded parts together.

118. In an apparatus of the character described, in combination, a source of cover web supply, a source of body web supply, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web, means adapted to slit the cover web longitudinally so as to dispose the slit between the severed edges of the body web, means adapted to sever the cover web transversely of said slit intermediate its ends, means adapted to fold rear portions of successive cover blanks around the rear ends of the body blanks and adhesively secure said folded parts together, and means adapted to press the adhesively secured blanks and cover web together as they are advanced.

119. In an apparatus of the character described, in combination, a source of cover web supply, a source of body web supply, a table on which said webs are adapted to move, means adapted to successively sever said body web transversely and adhesively secure the blank to the cover web, means adapted to fold successive front portions of

the cover web around the front ends of successive body blanks, respectively, and adhesively secure the folded parts, means adapted to advance the successive assembled body blanks and cover web, and the body web, means adapted to slit the cover web longitudinally so as to dispose the slit between the severed edges of the body web, means adapted to sever the cover web transversely of said slit intermediate its ends, means adapted to fold rear portions of successive cover blanks around the rear ends of the body blanks and adhesively secure said folded parts together, and rollers disposed on opposite sides of the path of said web materials adapted to yieldingly press them together as they advance.

120. In an apparatus of the character described, in combination, a source of cover web supply, a source of body web supply, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web, means adapted to slit the cover web longitudinally so as to dispose the slit between the severed edges of the body web, means adapted to sever the cover web transversely of said slit intermediate its ends, means adapted to fold rear portions of successive cover blanks around the rear ends of the body blanks and adhesively secure said folded parts together, and rollers disposed on opposite sides of the path of said web materials adapted to yieldingly press them together as they advance, one of said rollers having an elastic surface.

121. In an apparatus of the character described, in combination, a source of cover web supply, a source of body web supply, a table on which said webs are adapted to move, means adapted to successively sever said body web transversely and adhesively secure the blank to the cover web, means comprising oscillatory gripper jaws adapted to hold said webs stationary when being severed, means adapted to fold successive front portions of the cover web around the front ends of successive body blanks, respectively, and adhesively secure the folded parts, means adapted to advance the successive assembled body blanks and cover web, and the body web, means adapted to slit the cover web longitudinally so as to dispose the slit between the severed edges of the body web, means adapted to sever the cover web transversely of said slit intermediate its ends, and means adapted to fold rear portions of successive cover blanks around the

- rear ends of the body blanks and adhesively secure said folded parts together.
122. In an apparatus of the character described, in combination, a source of cover web supply, a source of body web supply, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web, means adapted to slit the cover web longitudinally so as to dispose the slit between the severed edges of the body web, means adapted to sever the cover web transversely of said slit intermediate its ends, and means adapted to fold rear portions of successive cover blanks around the rear ends of the body blanks and adhesively secure said folded parts together, said severing means for the body web and the cover web comprising a single reciprocatory support, cutting disks spaced apart thereon, one for the body web and another for the cover web co-operating resiliently operating presser rollers one on each side of the path of said web materials and between said disks, and means adapted to press the adhesively secured blanks and cover web together as they are advanced.
123. In an apparatus of the character described, in combination, a source of cover web supply, a source of body web supply, said body web having parallel longitudinal scores in line with lines on which the body web blanks are to be folded, the score adjacent one side of the web being at a distance from the adjacent edge of the web less than the distance of the opposite extreme folding score from its adjacent edge of the web, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web, means adapted to slit the cover web longitudinally in line with the extreme score farthest removed from the edge of the web and so as to dispose the slit between the severed edges of the body web, means adapted to sever the cover web transversely of said slit intermediate its ends, and means adapted to fold rear portions of successive cover blanks around the rear ends of the body blanks and adhesively secure said folded parts together, and means adapted to fold the adhering blanks transversely at the scored lines, and superpose the opposite sides of the cover web and adhesively secure the same.
124. In an apparatus of the character described, in combination, a source of cover web supply, a source of body web supply, said body web having parallel longitudinal scores in line with lines on which the body web blanks are to be folded, the score adjacent one side of the web being at a distance from the adjacent edge of the web less than the distance of the opposite extreme folding score from its adjacent edge of the web, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web, means adapted to slit the cover web longitudinally in line with the extreme score farthest removed from the edge of the web and so as to dispose the slit between the severed edges of the body web, means adapted to sever the cover web transversely of said slit intermediate its ends, and means adapted to fold rear portions of successive cover blanks around the rear ends of the body blanks and adhesively secure said folded parts together, and means adapted to fold the adhering blanks transversely at the scored lines, and superpose the opposite sides of the body web and cover web and adhesively secure the same.
125. In an apparatus of the character described, in combination, a source of cover web supply, a source of body web supply, said body web having parallel longitudinal scores in line with lines on which the body web blanks are to be folded, the score adjacent one side of the web being at a distance from the adjacent edge of the web less than the distance of the opposite extreme folding score from its adjacent edge of the web, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web, means adapted to slit the cover web longitudinally in line with the extreme score farthest removed from the edge of the web, and so as to dispose the slit between the severed edges of the body web, means adapted to sever the cover web transversely of said slit intermediate its ends, and means adapted to fold rear portions of successive cover blanks around the rear ends of the body blanks and adhesively secure said folded parts together, and means adapted to fold the adhering blanks transversely at the scored lines, and superpose the opposite sides of the cover web and adhesively secure the same.

said slit intermediate its ends, and means adapted to fold rear portions of successive cover blanks around the rear ends of the body blanks and adhesively secure said folded parts together, means adapted to fold the adhering blanks transversely at the scored lines, and superpose the opposite sides of the body web and cover web and adhesively secure the same, and means adapted to fold 10 the remaining portion of the cover blank around the edge of the superposed parts of the blank and adhesively secure the same thereto.

126. In an apparatus of the character described, in combination, a source of cover web supply, a source of body web supply, said body web having parallel longitudinal scores in line with lines on which the body web blanks are to be folded, the score adjacent one side of the web being at a distance from the adjacent edge of the web less than the distance of the opposite extreme folding score from its adjacent edge of the web, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web, means adapted to slit the cover web longitudinally in line with the extreme score farthest removed from the edge of the web, and so as to dispose the slit between the severed edges of the body web, means adapted to sever the cover web transversely of said 40 slit intermediate its ends, and means adapted to fold rear portions of successive cover blanks around the rear ends of the body blanks and adhesively secure said folded parts together and means adapted to fold the adhering blanks transversely at the scored lines, and superpose the opposite sides of the body web and cover web and adhesively secure the same and means adapted to fold the remaining portions of 50 the cover blank around the edge of the superposed parts of the blank and adhesively secure the same thereto and press the last mentioned folded parts.

127. In an apparatus of the character described, in combination, a source of cover web supply, a source of body web supply, said body web having parallel longitudinal scores in line with lines on which the body web blanks are to be folded, the score adjacent one side of the body web being at a distance from the adjacent edge of the web less than the distance of the opposite extreme folding score from its adjacent edge of the web, the sides of the body web being 60 beveled, means adapted to apply a line of

glue to each beveled edge of said body web, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web, means adapted to slit the cover web longitudinally so as to dispose the slit between the severed edges of the body web, means adapted to sever the cover web transversely of said slit intermediate its ends, means adapted to fold rear portions of successive cover blanks around the rear ends of the body blanks and adhesively secure said folded parts together, means adapted to fold the adhering blanks transversely at the scored lines and superpose the beveled portions of the body blank and the sides of the cover blank, the side of the body blank having the nearest adjacent score being located beneath the opposite side of said blank, and means adapted to fold the yet unfolded portions of the cover blank around the edge of the shell and adhesively secure and press the folded parts. 95

128. In an apparatus of the character described, in combination, a source of cover web supply, a source of body web supply, a table on which said webs are adapted to move, means adapted to successively sever said body web transversely and space the severed edges, means adapted to slit the cover web longitudinally so as to dispose the slit between the severed edges of the body web, means adapted to sever the cover web transversely of said slit intermediate its ends at a point spaced from the severed edges of the body web, means adapted to fold the portions of the cover web on one side of said slit and adjacent the severed edges thereof around the adjacent edges of the body sections and adhesively secure said parts comprising a transverse pair of jaws, a second transverse pair of jaws, means adapted to simultaneously move said pairs of jaws across the path of said web materials and thereby partially fold the cover material, means adapted to move one pair of jaws longitudinally rearwardly toward an adjacent edge of the body material and cause said jaws to inclose the adjacent body material and the folded cover material, and means adapted to move said body blank and cover blank rearwardly into the other pair of jaws. 110

129. In an apparatus of the character described, in combination, a source of cover web supply, a source of body web supply, a table on which said webs are adapted to move, means adapted to successively sever 130

5 said body web transversely and space the severed edges, means adapted to slit the cover web longitudinally so as to dispose the slit between the severed edges of the
 10 body web, means adapted to sever the cover web transversely of said slit intermediate its ends at a point spaced from the severed edges of the body web, means adapted to fold the portions of the cover web on one side of said slit and adjacent the severed edges thereof around the adjacent edges of the body sections and adhesively secure said parts comprising a transverse pair of jaws, a second transverse pair of jaws, means
 15 adapted to simultaneously move said pairs of jaws across the path of said web materials and thereby partially fold the cover material, means adapted to move one pair of jaws longitudinally rearwardly toward an adjacent edge of the body material and cause said jaws to inclose the adjacent body material and the folded cover material, means
 20 adapted to move said body blank and cover blank rearwardly into the other pair of jaws, and means adapted to cause relative motion between the jaws of each pair to press the folded parts therebetween.

130. In an apparatus of the character described, in combination, a source of cover web supply, a source of body web supply, a table on which said webs are adapted to move, means adapted to successively sever said body web transversely and space the severed edges, means adapted to slit the cover web longitudinally so as to dispose the slit between the severed edges of the body web, means adapted to sever the cover web transversely of said slit intermediate its ends at a point spaced from the severed edges of the body web, means adapted to fold the portions of the cover web on one side of said slit and adjacent the severed edges thereof around the adjacent edges of the body sections and adhesively secure said parts comprising a transverse pair of jaws, a second transverse pair of jaws, one jaw of said latter pair being longer than the other, means adapted to simultaneously move said pairs of jaws across the path of said web materials and thereby partially fold the cover material, means adapted to move said pairs of jaws longitudinally rearwardly toward an adjacent edge of the body material and cause one pair of jaws to inclose the adjacent body material and the folded cover material, a reciprocating plunger adapted to press the body blank and cover blank onto the said longer jaw, and means adapted to move said body blank and cover blank rearwardly into the other pair of jaws.

131. In an apparatus of the character described, in combination, a source of cover web supply, a source of body web supply, a table on which said webs are adapted to

move, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web, comprising coöperative gripper jaws, means adapted to bodily longitudinally reciprocate said jaws, means adapted to slit the cover web longitudinally so as to dispose the slit between the severed edges of the body web, means adapted to sever the cover web transversely of said slit intermediate its ends, means adapted to fold rear portions of successive cover blanks around the rear ends of the body blanks and adhesively secure said folded parts together, a mandrel, a carrier comprising coöperative blank gripping jaws, means adapted to reciprocate said carrier between said mandrel and one end of the path of said first mentioned gripper jaws, means adapted to cause said first mentioned gripper jaws to retain said blank until grasped by said carrier gripper jaws, and means adapted to fold successive assembled blanks around said mandrel.

132. In an apparatus of the character described, in combination, a source of cover web supply, a source of body web supply, a table on which said webs are adapted to move, means adapted to successively sever said body web transversely and adhesively secure the blank to the cover web, means adapted to fold successive front portions of the cover web around the front ends of successive body blanks, respectively, and adhesively secure the folded parts, means adapted to advance the successive assembled body blanks and cover web, and the body web, comprising parallel pairs of coöperative gripper jaws, means adapted to bodily longitudinally reciprocate said jaws, means adapted to slit the cover web longitudinally so as to dispose the slit between the severed edges of the body web, means adapted to sever the cover web transversely of said slit intermediate its ends, means adapted to fold rear portions of successive cover blanks around the rear ends of the body blanks and adhesively secure said folded parts together, a mandrel, a carrier comprising parallel pairs of coöperative blank gripping jaws, means adapted to reciprocate said carrier between said mandrel and one end of the path of said first mentioned gripper jaws, means adapted to cause said first mentioned gripper jaws to retain said blank until grasped by said carrier gripper jaws, and means adapted to fold successive assembled blanks around said mandrel.

133. In an apparatus of the character described, in combination, a source of cover

web supply, a source of body web supply, a table on which said webs are adapted to move, means adapted to successively sever said body web transversely and adhesively 5 secure the blank to the cover web, means adapted to fold successive front portions of the cover web around the front ends of successive body blanks, respectively, and adhesively secure the folded parts, means adapted 10 to advance the successive assembled body blanks and cover web, and the body web, means adapted to slit the cover web longitudinally so as to dispose the slit between the severed edges of the body web, 15 means adapted to sever the cover web transversely of said slit intermediate its ends, means adapted to fold rear portions of successive cover blanks around the rear ends of the body blanks and adhesively secure said 20 folded parts together, and means adapted to sever a longitudinal strip from the side of the cover blank.

134. In an apparatus of the character described, in combination, a source of cover web supply, a source of body web supply, a table on which said webs are adapted to move, means adapted to successively sever said body web transversely and adhesively 25 secure the blank to the cover web, means adapted to fold successive front portions of the cover web around the front ends of successive body blanks, respectively, and adhesively secure the folded parts, means adapted to advance the successive assembled 30 body blanks and cover web, and the body web, means adapted to slit the cover web longitudinally so as to dispose the slit between the severed edges of the body web, means adapted to sever the cover web transversely of said slit intermediate its ends, means adapted to fold rear portions of successive cover blanks around the rear ends of the body blanks and adhesively secure said 35 folded parts together, a longitudinally disposed mandrel a stationary shear blade adjacent said mandrel, a second shear blade adapted to be moved past the first to sever material, means adapted to transfer the successive blanks into folding position adjacent said mandrel and into trimming position adjacent said fixed blade, means adapted to operate the second blade to trim the edges of successive cover blanks, and means adapted to clear the second blade between its cutting movements. 40

135. In an apparatus of the character described, in combination, a source of cover web supply, a source of body web supply, a table on which said webs are adapted to move, means adapted to successively sever said body web transversely and adhesively 45 secure the blank to the cover web, means adapted to fold successive front portions of the cover web around the front ends of successive body blanks, respectively, and adhesively 50 secure the folded parts, means adapted to advance the successive assembled body blanks and cover web, and the body web, means adapted to slit the cover web longitudinally so as to dispose the slit between the severed edges of the body web, means adapted to sever the cover web transversely of said slit intermediate its ends, means adapted to fold rear portions of successive cover blanks around the rear ends of the body blanks and adhesively 55 secure said folded parts together, a longitudinally disposed mandrel a stationary shear blade adjacent said mandrel, a second shear blade adapted to be moved past the first to sever material, means adapted to transfer the successive blanks into folding position adjacent said mandrel and into trimming position adjacent said fixed blade, means adapted to intermittently rotate the second blade to trim the edges of successive cover blanks, a clearer, and means to draw the clearer along the movable blade between successive severing operations. 60

136. In an apparatus of the character described, in combination, a source of cover web supply, a source of body web supply, a table on which said webs are adapted to move, means adapted to successively sever said body web transversely and adhesively 65 secure the blank to the cover web, means adapted to fold successive front portions of the cover web around the front ends of successive body blanks, respectively, and adhesively 70 secure the folded parts, means adapted to advance the successive assembled body blanks and cover web, and the body web, means adapted to slit the cover web longitudinally so as to dispose the slit between the severed edges of the body web, means adapted to sever the cover web transversely of said slit intermediate its ends, means adapted to fold rear portions of successive cover blanks around the rear ends of the body blanks and adhesively 75 secure said folded parts together, a longitudinally disposed mandrel a stationary shear blade adjacent said mandrel, a second shear blade adapted to be moved past the first to sever material, means adapted to transfer the successive blanks into folding position adjacent said mandrel and into trimming position adjacent said fixed blade, means adapted to intermittently rotate the second blade to trim the edges of successive cover blanks, a clearer, and means to draw the clearer along the movable blade between successive severing operations. 80

137. In an apparatus of the character described, in combination, a horizontal table, a gluing device associated therewith, means adapted to intermittently longitudinally 85 feed a body web and a cover web on said table and superpose end portions of said webs, means adapted to guide said cover web into contact with said gluing device to coat the face thereof which is to lie adjacent the 90

138. In an apparatus of the character described, in combination, a horizontal table, a gluing device associated therewith, means adapted to intermittently longitudinally 95 feed a body web and a cover web on said table and superpose end portions of said webs, means adapted to guide said cover web into contact with said gluing device to coat the face thereof which is to lie adjacent the 100

- body web when superposed, transversely operable cutter disks adapted to successively sever blanks of different lengths from the respective webs, said feeding means comprising coöperative gripper jaws and means adapted to longitudinally bodily reciprocate said jaws, a head comprising longitudinally spaced folding and pressing jaws adapted to be located on opposite sides of the path 5 of the cover cutter disk, means adapted to move said head vertically and cause said jaws to simultaneously fold the cover material at both sides of the cutting line thereof, means adapted to move said head rearwardly after said vertical movement, and means whereby said gripper jaws are caused to move rearwardly after said vertical folding of said cover material. 10 75
138. In an apparatus of the character described, in combination, a horizontal table, a gluing device associated therewith, means adapted to intermittently longitudinally feed a body web and a cover web on said table and superpose end portions of said webs, means adapted to guide said cover web into contact with said gluing device to coat the face thereof which is to lie adjacent the body web when superposed, transversely operable cutter disks adapted to successively 25 sever blanks of different lengths from the respective webs, said feeding means comprising coöperative gripper jaws and means adapted to longitudinally bodily reciprocate said jaws, a head comprising longitudinally spaced folding and pressing jaws adapted to be located on opposite sides of the path of the cover cutter disk, means adapted to move said head vertically and cause said jaws to simultaneously fold the cover material at 30 80 both sides of the cutting line thereof, means adapted to move said head rearwardly after said vertical movement, and means whereby said gripper jaws are caused to move rearwardly after said vertical folding of said cover material. 15 85
140. In an apparatus of the character described, in combination, a table, means adapted to feed a body web and a cover web on said table, reciprocatory transversely operating cutters adapted to sever said webs into blanks of different lengths, the cover blanks being longer than the body blanks, mechanism adapted to superpose the cover blanks with the body blanks in pairs with 90 the ends of the cover blanks extending in front and in rear of the ends of the body blanks, pairs of combined folding and pressing jaws adapted to fold the extensions of the cover blanks over the ends of the body 95 blanks and press said elements together, and mechanism comprising a stationary mandrel, a pair of folding jaws and a presser, respectively oppositely disposed relatively to said mandrel, means adapted to successively transfer said blanks to the mandrel between said jaws and presser, means adapted to cause said jaws to move toward said mandrel and fold said assembled blanks transversely of said mandrel, superposing 100 the sides thereof, and means adapted to cause said presser to move toward said mandrel and press the superposed portions of 105 said folded blanks. 110
139. In an apparatus of the character described, in combination, a horizontal table, a gluing device associated therewith, means adapted to intermittently longitudinally feed a body web and a cover web on said table and superpose end portions of said webs, means adapted to guide said cover web into contact with said gluing device to coat the face thereof which is to lie adjacent the body web when superposed, transversely operable cutter disks adapted to successively sever blanks of different lengths from the respective webs, said feeding means comprising coöperative gripper jaws and means adapted to longitudinally bodily reciprocate 55 120 said jaws, a head comprising longitudinally 60 125 said jaws, a head comprising longitudinally 65 130
141. In an apparatus of the character described, in combination, a table, means adapted to feed a body web and a cover web thereon, reciprocatory transversely operating cutters adapted to sever said webs into blanks of different lengths, the cover blanks being longer than the body blanks, means adapted to superpose the cover blanks with the body blanks in pairs with the ends of the cover blanks extending in front and in rear of the ends of the body blanks, a reciprocatory dagger adapted to provide longitudinal slits in the extensions of the cover blanks in line with a folding line, pairs of combined reciprocatory folding and pressing jaws adapted to fold the extensions of the cover blanks 130

at one side of said slits over the ends of said body blanks and press the interfolded parts, a stationary mandrel, means adapted to successively transfer the assembled blanks to 5 said mandrel, pairs of folding and pressing jaws located respectively on opposite sides of said mandrel, means adapted to move one pair of folding and pressing jaws toward said mandrel to cause the blanks to be trans-
10 versely folded thereon and the ends of the body blanks superposed, and means adapted to move the other pair of pressing and folding jaws toward said mandrel to fold the remaining extended portions of the cover 15 blank longitudinally of the mandrel and press the interfolded parts.

142. In an apparatus of the character described, in combination, means adapted to superpose a body blank and a cover blank 20 with the cover blank projecting at opposite edges of the body blank, means adapted to fold said projecting portions of the cover blank around the respective adjacent edges of the body blank and secure the same there-
25 to, and means adapted to fold the resultant blank at an angle to said interfolded edges and connect the opposite sides thereof.

143. In an apparatus of the character described, in combination, means adapted to 30 assemble a body blank and a cover blank in superposed relation with the edges of the cover blank extending beyond the edges of the body blank at opposite sides of the latter and at an end adjacent said opposite 35 sides, means adapted to fold said opposite projecting portions of the cover blank onto the sides of the body blank adjacent thereto, means adapted to fold the resultant blank longitudinally of said opposite edges of said 40 body blank after said first mentioned folding and bring the opposite ends of the body blank toward each other, and means adapted to fold said remaining portion of the cover blank onto the other end of said body blank.

45 144. In an apparatus of the character described, in combination, means adapted to assemble a body blank and a cover blank in superposed relation with the interposition of adhesive and with the edges of the cover 50 blank extending beyond the edges of the body blank at opposite sides of the latter and at an end adjacent said opposite sides, means adapted to fold said opposite projecting portions of the cover blank onto the 55 sides of the body blank adjacent thereto, means adapted to fold the resultant blank longitudinally of said opposite edges of said body blank after said first mentioned folding and bring the opposite ends of the body 60 blank toward each other, and means adapted to fold said remaining portion of the cover blank onto the other end of said body blank, and adhesively secure the same thereto.

65 145. In an apparatus of the character de-

scribed, in combination, means adapted to assemble a body blank and a cover blank in superposed relation with the edges of the cover blank extending beyond the edges of the body blank at opposite sides of the latter and at an end adjacent said opposite sides, comprising a body web feeding mechanism and a body web severing mechanism, means adapted to fold said opposite projecting portions of the cover blank onto the sides of the body blank adjacent thereto, means adapted to fold the resultant blank longitudinally of said opposite edges of said body blank after said first mentioned folding and bring the opposite ends of the body blank toward each other, and means adapted to fold said remaining portion of the cover blank onto the other end of said body blank.

146. In an apparatus of the character described, in combination, means adapted to feed a pair of webs, means adapted to successively sever sections from each of said webs, the sections of one web being longer than those of the other, means adapted to superpose the sections of one web on the sections of the other in pairs so that the longer blanks overlap the opposite edges of the shorter blanks, means adapted to fold overlapping portions of the longer blanks around the adjacent edges of the shorter blanks onto the opposite faces of the latter and secure the same thereto, and means adapted to successively fold each pair of blanks at an angle to the said interfolded edges and connect the opposite sides thereof.

147. In an apparatus of the character described, in combination, a plurality of web gripping devices adapted to feed a plurality of webs, one of said devices adapted to be translated and the other comprising a pair of rollers, an oscillatory shaft, and connections between said shaft and said devices whereby one of said devices operates to feed its web in advance of the feed of the other web.

148. In an apparatus of the character described, in combination, a plurality of web gripping devices, one of said devices adapted to be translated and the other comprising a pair of rollers, an oscillatory shaft, a rack and pinion adapted to transmit motion to said translatable gripping device from said shaft, a pinion rotatable relative to said shaft, a gear adapted to transmit motion to said rollers and meshing with said second mentioned pinion, and a pawl and ratchet adapted to transmit motion from said oscillatory shaft to second mentioned pinion.

149. In an apparatus of the character described, in combination, a plurality of web feeding mechanisms, a plurality of mechanisms adapted to sever blanks from said webs, web folding mechanism, means whereby the aforesaid mechanisms automatically coöperate to form a composite blank com-

- posed of a section of one web disposed on the opposite faces of a section of another web and across one edge thereof, and mechanism comprising a stationary angular former 5 adapted to fold said composite blank on lines transverse to said edge into a tubular element.
150. In an apparatus of the character described, in combination, a plurality of web feeding mechanisms, a plurality of mechanisms adapted to sever blanks from said webs, web folding mechanism, means whereby the aforesaid mechanisms automatically coöperate to form a composite blank composed of a section of one web disposed on the opposite faces of a section of another web and around opposite edges thereof, and mechanism comprising an angular former adapted to fold said composite blank on lines 20 transverse to said edges into a tubular element.
151. In an apparatus of the character described, in combination, a plurality of web feeding mechanisms, a plurality of mechanisms adapted to sever blanks from said webs, web folding mechanism, means whereby the aforesaid mechanisms automatically coöperate to form a composite blank composed of a section of one web disposed on the opposite faces of a section of another web and across opposite edges thereof, and mechanism comprising a stationary angular former adapted to fold said composite blank on lines transverse to said edges into a tubular element.
152. In an apparatus of the character described, in combination, means adapted to feed a pair of webs and assemble the ends in superposed relation with the interposition 40 of adhesive comprising a stationary table to support the web ends, means adapted to sever said webs on lines to produce a composite blank composed of said superposed ends, means adapted to fold said composite blank into a shell, a reciprocatory gripper adapted to move the superposed portions of the webs in the direction of said folding means, and a second reciprocatory gripper adapted to further move the com-
- posite blank and place it in position to be 50 folded.
153. In an apparatus of the character described, in combination, means adapted to feed a pair of webs and assemble the ends thereof in superposed relation with the interposition of adhesive comprising a stationary table to support the web ends, means adapted to sever said webs on lines to produce a composite blank composed of said superposed ends, and means adapted to fold 60 said composite blank into a shell comprising a stationary former around which said blank is to be folded.
154. In an apparatus of the character described, in combination, means adapted to 65 produce from a pair of webs a shell blank composed of a superposed cover blank and body blank, with the side of the cover blank extending beyond the adjacent side of the body blank, shell blank folding mechanism, 70 shearing mechanism, means adapted to feed said shell blank into position to be folded by said shell blank folding mechanism, and means adapted to cause said shearing mechanism to trim said extending side of said 75 cover blank prior to the folding of said shell blank into a shell.
155. In an apparatus of the character described, in combination, means adapted to produce from a pair of webs a shell blank 80 composed of a superposed cover blank and body blank, with the side of the cover blank extending beyond the adjacent side of the body blank, shell blank folding mechanism, shearing mechanism, means adapted to feed 85 said shell blank into position to be folded by said shell blank folding mechanism, and means adapted to cause said shearing mechanism to trim said extending side of said cover blank while said shell blank is in said 90 position to be folded by said folding mechanism.

In testimony whereof I affix my signature, in the presence of two witnesses.

CARLOS HOLLY.
